UNITED STATES PATENT OFFICE

2,031,329

AUTOMATIC TELEPHONE SYSTEM

John E. Ostline, Berwyn, Ill., assignor to Automatic Electric Company, Limited, Liverpool, England, a British company

Application September 6, 1934, Serial No. 742,887

26 Claims. (Cl. 179—16)

This invention relates in general to automatic telephone systems, and the object of the invention, broadly stated, is the provision of new and improved automatic switching and controlling apparatus for use in an automatic telephone exchange.

This invention may be considered as an improvement of the system disclosed in the Wicks patent No. 1,732,186, issued October 15, 1929, 10 wherein uni-directional rotary type switches are controlled by register senders according to the revertive system of control.

Another object of the invention is to provide an improved switch positioning circuit arrangement 15 whereby the stepping speed of the switches need not be within any particular limits because the register controller for controlling the switch operations will always wait until the proper switch position is reached.

One feature of the invention relates to the primary and secondary finders which have no associated relays or spark quenching equipment; such switches being controlled from the common register controller.

Another feature relates to an improved method 20 of assigning register controllers for use in response to the initiation of calls. When calls come in rapidly register controllers are assigned on following calls before a preceding one has been 25 connected with the calling line.

Another feature relates to a repeater which repeats the revertive control conditions between two exchanges on inter-exchange calls.

The invention, its features and operation will 30 be described in detail in the following specification with the aid of the accompanying drawings comprising Figs. 1 to 10, inclusive. Fig. 1 discloses a so-called one-line diagram showing the trunking system for two 500-line groups. Fig. 1a 35 shows the manner in which Figs. 2 to 10, inclusive, are to be arranged with the corresponding lines in alignment. Figs. 2 to 10, inclusive, show by means of the usual circuit diagram the new and improved selector, connector, combination 40 call controller and sufficient of the associated apparatus to render possible a thorough understanding of the invention.

Referring now to the upper portion of Fig. 1, the subscribers' lines are divided into groups of 45 five hundred lines and these groups are again divided into groups of one hundred lines. The squares designated 100 shown in the upper left-hand corner represent each 100 line circuits which are connected to the banks of the primary line finders, there being ten primary line finders

for each one hundred line circuits. The primary line finders terminate in primary trunks which are multiplied in the banks of the secondary line finders and in the banks of the group finders associated with the call controllers. The secondary line finders terminate in secondary trunk relay groups and in first group selectors. There are as many secondary line finders and secondary trunk relay groups as is needed to take care of the traffic originating in this 500 line group. The 10 banks of the first group selectors extend to second group selectors and are multiplied in the manner illustrated. The second group selectors have access to connectors and the connectors in turn have access to the line circuits of the subscribers' lines in the usual manner. Each 100 group of subscribers' lines has a start lead extending to a start relay associated with the allotter. The allotter has access to as many combination call controllers as is required for the 15 traffic in this sub-group of lines. As previously stated, the group finder of each call controller is multiplied to the primary trunks, while a secondary trunk finder associated with each call controller is used for selecting an idle secondary 20 trunk relay group. The combination call controller has a number of relays and switches which will be described more fully in connection with the remaining figures. The lower portion of Fig. 1 shows the second or last 500 line group which 25 is similar to the upper portion and is shown in order to show the usual trunking connections between the first and second selectors.

In Fig. 2 the circle at the extreme left indicates subscriber A, whose number in this case 35 is 1121. The line conductors 1 and 2 extend from the telephone to the line circuit comprising relays 10 and 20. Conductors 1, 2 and 3 are the connector normals and extend by way of cable 4 to the connector bank shown in Fig. 5. Conductors 6 and 7 are the start conductors for marking the calling group and for initiating the operation. The calling end of the line circuit terminates in the banks of the primary line finder. Mechanically, the switch mechanism of the primary line 45 finder is similar to the switch mechanism of the well-known rotary line switch, except that it has been provided with two sets of single ended multiply connected wipers mounted on the same shaft, wipers 101, 103, 105 and 107 being one set, 50 and wipers 102, 104, 106 and 108 being the other set. A separate set of banks is provided for each set of wipers, the two sets of banks being placed side by side. These two sets of wipers are positioned on the shaft 180 degrees apart so that 55

when one set of wipers is moved off the last set of contacts on its associated set of banks, the other set of wipers is moved on to the first set of contacts in its associated set of banks. Since each bank shown has a capacity of 50 lines the primary finder therefore has access to 100 subscribers' lines. In this case each primary line finder comprises only the wipers and banks and the motor magnets for controlling the operation of the finder.

The primary line finders terminate in the primary trunks which terminate in the banks of secondary line finders and in the banks of the group finders associated with the combination call controllers. The secondary line finder shown in Fig. 2 comprises a 50-point switch similar in the mechanical construction and operation to the well known rotary line switch. Each secondary line finder terminates in a secondary trunk relay group which is shown in Fig. 3.

The secondary trunk relay group shown in Fig. 3 comprises relays for feeding talking battery to the calling and called subscribers and for maintaining the connection after the combination call controller is released. In the bottom portion of Fig. 3 is shown the wipers of the secondary trunk finder associated with the particular combination call controller shown in Figs. 6, 7, 8 and 9. Each secondary trunk relay group is connected to a first group selector such as shown in Fig. 4. The first group selector shown in Fig. 4 comprises a number of relays and a motor magnet for operating the wipers of the selector over its bank contacts. The wipers and banks are arranged mechanically similar to the wipers and banks of the primary line finder and in this case the first group selector wipers have access to one hundred second group selectors indicated by the rectangle. In addition the bank contacts are divided up into groups of ten contacts each and are numbered in the manner diagrammatically illustrated for the bank contacts accessible to wipers 341 and 342. The wipers of the first selector are always returned to their normal position in which position the off normal springs 315 and 316 are opened as illustrated. One of the trunks, accessible in the fourth group of bank contacts of the first selector and in the fourth group of bank contacts of the other similar first selectors, is shown comprising conductors 352, 356 and 358, terminating in the second group selector shown by the rectangles in Fig. 4. The second group selector is identical in circuit operation and in mechanical construction to the first selector shown. The banks of this second selector as well as the banks of similar second selectors are connected to a number of groups of connector switches in the well known manner.

The connector shown in Fig. 5 is accessible to the fifth group of trunks in the second selectors. The connectors are mechanically similar to the group selectors and each comprise six relays and a motor magnet for controlling the operation of the connector wipers. The wipers of the connector have access to one hundred lines and are restored to normal upon the release of the connection. The banks of the connector are likewise divided into ten groups of lines and the lines terminate in the connector banks in these groups in the manner indicated by the numbering associated with the banks accessible to wipers 471 and 472. To the right of the connector in Fig. 5 is shown the line circuit, the primary line finder banks and the subscriber's telephone station B.

A number of two-step relays have been shown in the selector and connector switches which relays upon energizing in their first step operate only the armatures designated by roman numerals I, while in their second step the armatures designed by the roman numerals II are operated.

At the extreme left of Fig. 6 is shown the allotter and associated start relays 31 and 41 for two of the one hundred line groups, it being understood that a relay, such as 31 or 41, is provided for each hundred line group. The start conductors 6 and 6' each extend from a hundred line group to wiper 33 of the allotter. The allotter has access to as many combination call controllers as are needed to take care of the traffic originating in this five hundred line group. The upper portion of Fig. 6 shows the wipers of the group finder associated with the particular combination call controller shown in Figs. 7, 8 and 9. As shown, the wipers of the group finders have access to primary trunks such as the one shown in Fig. 2. The marking conductors 7 and 7' extend through start relays, such as relays 31 and 41, and are connected to multiplied bank contacts accessible to wipers 611 in the group finder to mark the calling group. The mechanical construction and operation of the group finder is similar to the mechanical construction and operation of the well known rotary line switch. Both the group finder and the secondary trunk finder are part of the combination call controller shown in Figs. 7, 8 and 9.

In Fig. 7 are shown a number of the relays of one of the combination call controllers. Relay 740 in Fig. 7 has a weighted armature 741 with a weight 742 on its right-hand end, which starts vibrating between contacts 743 and 744 when the armature is released. The relays shown in Fig. 8 are also part of this combination call controller. In the extreme right of Fig. 8 is shown the counting switch CS which is mechanically similar to an eleven point rotary line switch in which the wipers are restored to normal position and in which the wipers are advanced one step upon each energization of the motor magnet 885. In Fig. 9 is shown the sending control switch X comprising wipers 913 to 915, inclusive, the motor magnet 910 which advances the wipers one step upon each de-energization and the off-normal springs 912 for controlling the restoration of the wipers after the sending operation. The sending control switch X is mechanically similar to the counting switch CD. The sequence switch SS and the four register switches RA, RB, RC and RD are mechanically similar to the well known rotary line switch, but in this case the wipers of the respective switches are operated one step upon each energization of its associated motor magnet. Each of these latter switches have off normal springs for controlling the restoration of the switch wipers after the sending operation.

Fig. 10 discloses a make busy relay 560 located in a distant office and two trunk conductors 505 and 507 extending to the local exchange where-in the line conductors terminate in the repeating coil R3, and an incoming repeater comprising a plurality of relays. Relays 510 and 520 are polarized relays which operate only when current is sent through their windings in the proper directions. The incoming repeaters terminate in second group selectors which have access to the connector switches in the manner illustrated in Fig. 4.

General operation

For the purpose of this description it has been assumed that the subscribers' lines are arranged in groups of five-hundred lines, that each one hundred line group has ten primary line finders, and that these primary line finders are concentrated through the second line finders into a group of thirty secondary trunks. Each primary trunk 5 comprises a primary line finder for finding the calling line and this trunk terminates in the secondary finder banks for the purpose of establishing the final connection. Each primary trunk is also multiplied to the banks of the group finders 10 for the purpose of associating a combination call controller with a calling line. Each secondary trunk consists of a fifty-point secondary line finder for finding primary trunks and associated with each secondary trunk is also a group of secondary trunk relays for holding the connection, 15 for controlling the metering and feeding talking battery to both calling and called subscribers. These secondary trunk relay groups terminate in first group selectors.

20 When a subscriber initiates a call the line relay in his line circuit operates in the usual manner to initiate the operation of an idle call controller through the allotter and to mark the calling group in the bank of the group finder of the selected controller and to mark the calling line in the banks 25 of the primary finders. The group finder associated with the allotted controller will first of all find a free primary trunk within the particular sub-group of one hundred lines where the call originated. As soon as this operation has taken 30 place, the primary finder associated with the selected primary trunk will start hunting for the calling line. As soon as the calling subscriber's line has been found the subscriber's cut-off relay 35 operates and the connection is switched through to the controller.

It will be apparent from the foregoing description that for each call originated, two selecting motions are required to find the calling line. 40 Owing to the fact that call controllers may serve a maximum of five one hundred line sub-groups, it may appear possible that long waits for the dial tone will result when calls are started simultaneously in different sub-groups. This is prevented by the following arrangement. If, for instance, calls are originated in three sub-groups at 45 practically the same instant, the first controller taken into use will find, via its group finder, the sub-group in which the call has originated, at this point, and before the calling subscriber's line has 50 actually been found, a second call controller will be started by the advance of the allotter to take care of the second call, and so on. In other words, each succeeding call, if in a different sub-group, 55 need not wait for the complete selection of the calling subscriber's line, but only long enough for an allotted call controller to find a free trunk within a sub-group where the call has started.

As soon as the calling subscriber is connected 60 with the controller, dial tone is placed on the line indicating that dialling of the desired number can now take place. The dial pulses are then stored in the call controller on the register switches RA to RD, inclusive. As soon as 65 the call controller is taken into use, its associated secondary trunk finder starts hunting for a free secondary trunk. As soon as the trunk is found, it is held in readiness by the call controller to receive the transmission of a call as 70 fast as the subscriber's dial pulses are stored

75 on the register switches. Immediately after the seizure of the primary trunk by the group finder and the secondary trunk by the trunk finder, a local circuit is set in motion whereby the secondary line finder associated with the secondary trunk seized is stepped to the primary trunk over which the call is being dialled in by the calling subscriber. This connection between the primary and the secondary trunk is made entirely independent of all other functions taking place 10 at the same time and does not require any relays or equipment, other than that contained in the call controller, for its completion. After the secondary line finder has been associated with the proper primary trunk, the circuit between it 15 and the secondary trunk remains open.

Instead of sending stepping impulses to the selectors and connectors to place their wipers in front of a desired group, the seizure of a selector or connector will cause it to step by self-inter- 20 ruption to the beginning of the first trunk group in the case of a group selector or to the first "tens" group in the case of a connector. At this point a signal is sent to the call controller by a charge of current strength. This change pro- 25 duces a momentary release and reoperation of the line relay in the selector and the same process is repeated until the wipers stand at the beginning of the desired group; the desired group being determined by the position of the register 30 switches in the controller. With this kind of stepping operation the stepping speed of the switch need not be within any particular limits because the controller will always wait until the proper position has been reached. Assuming that 35 the line called is available, the connector switch will signal this fact to the call controller as soon as a connection has been established. At this instant, a call controller and its associated group 40 finder and trunk finder release from the connection and a talking circuit is established from the subscriber's line by way of the primary line 45 finder, the secondary line finder, the secondary trunk relay group, its associated first group selector, and selected second selector and connector.

In case one of the selectors encounters a busy 50 or in case the called line is busy, the entire connection, including the first selector and second selector, is instantly released and made available for other calls, and busy tone is transmitted 55 from the call controller to the calling subscriber.

Having given a general description and operation of the system a detailed description will now be given. For this purpose it will be assumed that subscriber A initiates a call and in response to the removal of his receiver the following circuit for line relay 10 is completed; from grounded armature 23, conductor 2, substation loop, conductor 1, armature 21 and through 60 the winding of line relay 10 to grounded battery. At armature 11 relay 10 disconnects the winding of cut-off relay 20 from the connector normal conductor 3 and connects battery through 65 the winding of relay 20 by way of conductor 5 to the bank contacts in the primary line finders to mark the calling line. At armature 12 relay 10 grounds conductor 6 to complete a circuit for 70 vibrating relay 740 in the controller as follows: from grounded armature 12, conductor 6, armature 32, wiper 33 of the allotter which has pre-selected this idle call controller, conductor 628, armature 715 and through the upper winding of 75 relay 740 to battery. At armature 13 relay 10 marks the calling group in the banks of the group

finders associated with the call controllers by marking as many multiple bank contacts accessible to wipers, such as wiper 611, as there are primary finders in this calling one hundred line group. This group marking enables the group finders to locate the particular hundred line group which is calling. Relay 740 operates its weighted armature 741 to close contacts 743, thereby completing a circuit for energizing slow 10 to release relay 750 by way of armature 762. Relay 750, upon energizing, at armature 751 connects the test wiper 275 of the secondary trunk finder to the upper winding of the secondary trunk finder test relay 770; at armature 752 15 closes a self interrupting circuit by way of armature 733 and conductor 288 to the motor magnet 290 of the secondary trunk finder; at armature 753 prepares a point in the circuit for connecting dial tone to the calling line, at armature 754 prepares a holding circuit for relay 770; at armature 755 completes a locking circuit for itself independent of armature 762; at armature 756 completes an energizing circuit for slow to operate relay 720; and at armature 757 prepares a stepping circuit for sending control switch X. Motor magnet 290 of the secondary trunk finder energizes over the above traced circuit and at its interrupter springs 289 interrupts its own circuit whereupon the motor magnet deenergizes and advances the wipers one step 30 for each deenergization. The motor magnet 290 interrupts in a buzzer-like manner to advance the wipers of the secondary trunk finder step by step until test wiper 275 engages an idle 35 trunk having negative battery potential on the bank contact encountered by wiper 275. When test wiper 275 encounters an idle trunk test relay 770 energizes over the following circuit: from ground through the upper winding of test relay 40 770, armature 751, conductor 285, test wiper 275, control conductor 256, and through the upper windings of relays 320 and 330 in the first group selector to grounded battery. Test relay 770 alone energizes over this circuit and at armature 45 771 prepares a circuit for grounding the negative conductor 252 or the positive conductor 268, dependent upon the operated condition of relay 810. At armature 772 relay 770 prepares a circuit for connecting grounded battery through the 50 winding of relay 830 to the negative conductor 252 or positive conductor 258, dependent upon the operated condition of relay 810. At armature 773 relay 770 immediately opens the circuit of motor magnet 290 to cause the wipers of the 55 secondary trunk finders to stop on the idle trunk selected; at armature 774 prepares a point in the circuit for release relay 210 in the secondary trunk relay group; at armature 775 connects up the spark quenching condenser and the resistance 60 779 to motor magnet 161 of the secondary line finder; at armature 776 prepares a circuit for energizing the A. C. relay 790; at armature 777 prepares a circuit for relay 780 which is short circuited from ground at armature 791; and at armature 778 short circuits the upper winding of 65 test relay 770 to connect direct ground to conductor 256 by way of armature 751, conductor 285, and wiper 275 to energize the two-step relay 320 in the first group selector in its first step to operate only armature 324. Relay 330 being marginal will not energize over its upper winding in parallel with the upper winding of relay 320. Relay 320 operates only its armature 324 to open the restoring circuit of the first group selector. 70 75 Slow to operate relay 720 energizes over the

following circuit: from grounded wiper 913 of the sending control switch in engagement with its first or normal position bank contact, conductor 792, armature 755 and through the winding of relay 720 to battery. At armature 721 relay 720 closes a self interrupting circuit to the motor magnet 618 of the group finder by way of armature 711 and conductor 620; at armature 722 completes the holding circuit through the lower winding of test relay 770 and completes holding circuits for relays 700 and 710 through their upper windings, but these latter relays, being marginal, do not energize at this time over their upper windings; at armature 723 prepares a point in the circuit of the group finder test 15 relay 710 and at armature 724 closes a circuit for shunting the lower winding of group finder test relay 710 when the group finder test wiper 614 encounters a busy primary trunk. Whenever wiper 614 engages a grounded bank 20 contact indicating a busy primary trunk, a circuit for shunting the lower winding of group finder test relay 710 may be traced as follows: from the grounded bank contact engaged by wiper 614, conductor 624, armature 712 and 25 resting contact, armatures 724 and 723, lower winding of group finder test relay 710 and by way of resting contact and armature 705 to ground. When the group test wiper 611 of the group finder encounters one of the multiple connected bank contacts having group calling battery potential connected thereto at the time the primary test wiper 614 does not encounter a grounded bank contact a circuit may be traced for energizing the group finder test relay 710 30 as follows: from ground by way of armature 705 and resting contact, lower winding of group finder test relay 710, armature 723, conductor 627, group test wiper 611, through one of the multiplied bank contacts through the winding of relay 31, common start conductor 7 for this hundred line group, armature 13 and by way of the resistance to grounded battery. Relay 31 energizes in series with group test relay 710, and at armature 32 disconnects start ground from 40 wiper 33 in case no other line is calling. Group test relay 710, upon energizing in series with relay 31 when the calling group is found, at armature 711 opens the circuit to motor magnet 618 to stop the wipers of the group finder on the 50 bank contacts terminating an idle primary trunk; at armature 712 and resting contact opens the shunt circuit through the lower winding of relay 710, and at its working contact prepares the test circuit to the line test relay 700 which will 55 operate when the selected primary line finder finds the calling line. At armature 713 relay 710 grounds conductor 625 by way of armature 706 to complete a circuit for operating the motor magnet 118 of the selected primary line finder; at armature 714 closes a common spark quenching circuit for the connected motor magnet of the primary line finder; at armature 715 opens the circuit to the upper winding of relay 740, and at armature 716 grounds conductor 629 to 60 energize motor magnet 35 of the allotter to cause the wipers of the allotter to be stepped in search of an idle combination call controller which will be used on a subsequent call. The circuit for operating the allotter magnet 35 extends by way of grounded conductor 629, bank contacts engaged by wiper 34, interrupter springs 36 and through the winding of motor magnet 35 to battery. Motor magnet 35 operates in the manner of a buzzer as long as wiper 34 engages 70 75

grounded bank contacts to step the wipers of the allotter to an idle call controller. The circuit for energizing the motor magnet 118 of the primary line finder may be traced as follows: from ground by way of armature 113, armature 706, conductor 625, wiper 613, conductor 121, interrupter springs 119 and through the winding of motor magnet 118 to grounded battery. Motor magnet 118 operates in the manner of a buzzer interrupting its own circuit at interrupter springs 119 until such time as line test relay 100 energizes and opens the circuit thereto at armature 706. During the stepping operating of motor magnet 118 the common spark quenching circuit is completed by way of conductors 120 and 626 to the condenser 716 and resistance 717 to ground at armature 714.

Relay 140 deenergizes when its circuit is opened at armature 715 or by the operation of the allotter, and upon deenergizing releases its armature 741 thereby causing the weight 742 thereon to vibrate between springs 743 and 744 for a predetermined period. Each time armature 741 engages springs 743 or 744 the circuit through slow to release relay 750 is again completed to maintain this relay energized. The weight 742 on armature springs 741 may be adjusted so that this spring may vibrate for a variable number of seconds before it finally comes to rest between the two springs 743 and 744. In the instant disclosure it is assumed that the weighted armature 741 will vibrate for a period of approximately four seconds and therefore hold relay 750 energized during that period. Relay 750 in the normal operation of the system, however, should not deenergize unless some fault occurs or unless the calling subscriber fails to dial within the required period. The test conductors of busy subscribers' lines are grounded and therefore when the test wiper 105 or 106 of the primary line finder encounters a grounded bank contact terminating a busy line, a circuit may be completed over conductor 115, wiper 614, conductor 624, armature 712 and working contact and through the lower winding of line test relay to ground for short relay 100. Line test relay 100 being short circuited will not energize over this circuit. When a calling line is found, test wiper 105 or 106 will encounter a calling battery potential extending through the winding of cut-off relay 20 and armature 22 in parallel for energizing line test relay 100 over the previously traced circuit. Line test relay 100, upon energizing, at armature 701 grounds conductor 281 to close a self interrupting circuit to the motor magnet 161 of the secondary line finder; at armature 102 connects up a circuit to the secondary winding of transformer T in series with the A. C. relay 790; at armatures 703 and 704 completes a circuit including the calling subscriber's loop for energizing line relay 730; at armature 705 grounds conductors 624 and 115 to operate the cut-off relay 20, and to mark the primary trunk busy, and at armature 706 opens the circuit to motor magnet 118 to stop the wipers of the primary line finder on the bank contacts terminating the calling line. Cut-off relay 20, upon energizing, at armatures 21 and 23 disconnect the line relay 10 and ground from the line conductors 1 and 2, at armature 22 disconnects battery at its resting contact and at its working contact completes a locking circuit for itself from conductor 5 now grounded over conductor 115. Line relay 10 deenergizes and at armature 11 busies the called test conductor 3 by connecting ground thereto by way of grounded conductor 115, wiper 105, con-

ductor 5, working contact and armature 22, armature 11 and resting contact, to conductor 3. At armature 12 relay 10 removes ground from conductor 6 to remove the start ground condition and at armature 13 disconnects group marking battery from conductor 7 and relay 31. The circuit for relay 31, was opened at armature 705 in response to the operation of the test relay 100. In addition the operation of relay 100 at armature 705 opens the original energizing circuit of group test relay 710 and also at the working contact of springs 705 short circuits the lower winding of relay 700 but both these relays, 700 and 710, are now maintained energized solely over their upper windings from grounded armature 722.

A circuit for energizing line relay 730 in the call controller may be traced as follows: from ground through the lower winding of relay 730, armature 704, conductor 623, wiper 615, conductor 117, wiper 107, conductor 2, through the calling substation loop of subscriber A, conductor 1, wiper 101, conductor 111, wiper 616, conductor 622, armature 703, and through the upper winding of line relay 730 to grounded battery. At armature 731 line relay 730 completes an obvious circuit for energizing slow to release relay 760. At armature 761 relay 760 connects dial tone to the calling subscriber's line as follows: from dial tone source (Fig. 9) by way of off normal springs 933, conductor 789, working contact and armature 153, 30 armature 761, tone condenser TC, armature 703, conductor 622, wiper 616, conductor 111, wiper 101, conductor 1, to the calling substation loop. At armature 762 relay 760 opens the original energizing circuit of relay 750, but this relay is maintained in operated position through its own armature 755; at armature 763 closes a shunt around armature 756 to maintain release relay 720 in energized position; at armature 764 completes a circuit from grounded armature 815 and conductor 793 through the lower winding of relay 140 to grounded battery to again energize relay 740 in order to maintain slow to release relay 750 in energized position. At armature 765 relay 760 completes a circuit for energizing relay 870 as follows: from ground by way of armature 765, conductor 794, and through the winding of relay 870 to grounded battery. At armature 766 relay 760 completes a circuit for energizing motor magnet 920 of the sequence switch SS as follows: from ground by way of armature 766, conductor 798, armature 901, and through the winding of motor magnet 920 to grounded battery. Motor magnet 920 energizes over the above traced circuit and steps wiper 923 in engagement with its first bank contact, and operates its interrupter spring 921. Off normal springs 922 of the switch SS close in response to wiper 923 engaging the first bank contact.

Relay 870, upon energizing, at armature 871 60 connects an A. C. source through the primary winding of transformer T by way of conductors 787 and 788. At armature 872 relay 870 opens a point in the self restoring circuit of counting switch CS; at armature 873 prepares a circuit for relay 820, at armature 874 prepares a point in the locking circuit of relay 840; and at armatures 875 to 882, inclusive, disconnects grounded relay 889 from the sending control switch X, the sequence switch SS and the register switches 70 RA, RB, RC and RD; in order to open the restoring circuits of such switches.

The circuit for operating motor magnet 161 of the secondary line finder may be traced as follows: from ground by way of armature 791, rest- 75

ing contact and armature 782, armature 777, armature 701, conductor 281, wiper 271, conductor 164, interrupter springs 162 and through the winding of motor magnet 161 to grounded battery. Motor magnet 161 operates in the manner of a buzzer to advance the wipers of the secondary line finder step by step until wiper 159 finds the conductor marked by the group finder associated with the call controller in use. 5 The conductor marked by the group finder corresponds to the primary trunk taken into use and in this case is the conductor 122, and therefore when wiper 159 engages the bank contact terminating conductor 122 a circuit is completed 10 for A. C. relay 790 as follows: from the right-hand terminal of A. C. relay 790 through the secondary winding of transformer T, conductor 283, wiper 273, conductor 160, wiper 159, conductor 122, wiper 617 of the group finder, conductor 621, armatures 702, 776 and 781 to the left-hand terminal of A. C. relay 790. Since the circuit to the primary winding of transformer T has previously been closed by the operation of armature 871, A. C. relay 790 is energized over 15 the above traced circuit. At armature 791 relay 790 opens the stepping circuit to motor magnet 161 and stops the secondary line finder in engagement with the primary trunk taken into use by the group finder and also removed a ground shunt from the winding of relay 780 which now operates from battery through the winding of motor magnet 161. Due to the high resistance winding of relay 780 motor magnet 161 does not operate in series therewith with the result that the wipers of the secondary line finder stop in engagement with the selected primary trunk. At armature 781 relay 780 opens the circuit of A. C. relay 790 which now de- 20 energizes and at armature 782 locks itself independent of armature 777 in case relay 770 should deenergize.

A brief review will now be given of the operations which have resulted from the initiation of a call prior to the calling subscriber dialling the 25 desired called subscriber's number. (1) The allotter has assigned an available call controller. (2) The controller has placed its associated group finder on an available primary trunk to the calling hundreds group. (3) The controller at this time steps the allotter forward so that another call controller may be started if there are other calls waiting. (4) The call controller steps the primary line finder associated with the primary trunk selected to the calling line. (5) The secondary trunk finder associated with the controller in use has selected a free secondary trunk and with it a first selector. (6) The call controller has stepped the secondary line finder associated with the selected secondary trunk relay group to a position where it can connect with the primary line finder already selected by the controller. This placing of the secondary line switch in association with the primary line finder does not establish any circuit connection. (7) The calling subscriber's dial telephone is now connected with the controller and the controller is connected with the first selector. The equipment between the first selector and the primary line finder, that is, the secondary line finder and the secondary trunk relay group, permanently associated with the secondary trunk, are held in readiness for the completion of the connection, but are not as yet in the circuit nor do they perform any function in the 30 setting up of the connection.

The calling subscriber may now dial the digits corresponding to the called subscriber's telephone number and in this case we will assume that the calling subscriber dials the digits 4-5-6-7. In response to the first digit or 5 digit 4 line relay 730 deenergizes four times and each time transmits a ground pulse by way of armature 732 over conductor 797, through the winding of relay 900, wiper 923 in engagement with its first blank contact, and through the 10 winding of motor magnet 930 of the first digit storing switch or register switch RA to grounded battery. Storing or register switch RA being of the direct drive type steps its wiper 934 one step in response to each energization of motor 15 magnet 930 and since four ground pulses are transmitted thereto by way of armatures 766 and 732, wiper 934 will come to rest in engagement with its fourth bank contact terminating the No. 4 conductor included in cable 890. In 20 response to the first step of wiper 934 off normal springs 933 disconnects dial tone from the calling line and also operates the off normal springs 932 to prepare the restoring circuit for switch RA, which, however, is open at this time at armature 877. Relay 900 energizes in series with motor magnet 930 and due to its slow release characteristics maintains its armature 901 operated for the duration of the impulses in each digit. At armature 901 relay 900 therefore 30 opens the circuit to motor magnet 920 which accordingly deenergizes. At the end of the first digit slow to release relay 900 deenergizes and again completes the circuit for energizing motor magnet 920 to again cause the sequence switch 35 wiper 923 to step into engagement with its second bank contact to prepare the second register or storing switch RB for the second digit.

In response to the calling subscriber dialling the second digit, or digit 5, line relay 730 de- 40 energizes five times and in response to these de-energizations completes the following circuit: from ground by way of armature 766, armature 732, conductor 797, through the winding of slow to release relay 900, wiper 932 in engagement 45 with its second bank contact and through the winding of motor magnet 940 of the second register or storing switch RB to negative battery. Motor magnet 940 operates five times and sets the wiper 944 into engagement with its fifth contact terminating the No. 5 conductor in cable 890. In response to the first step of wiper 944 off normal springs 943 completes a circuit for energizing relay 820 in order to retransmit the first digit stored to the first group selector, and at the off 55 normal springs 942 prepares the restoring circuit for switch RB. Slow to release relay 900 operates in the same manner as before to open the circuit to motor magnet 920 and shortly after the second digit relay 900 deenergizes to again complete the circuit for operating motor magnet 920 to step its associated wiper 923 into engagement with its third bank contact in readiness to register the third digit.

In response to the calling subscriber dialling the third digit, or digit 6, line relay 730 is deenergized six times and each time transmits a ground impulse through relay 900 and wiper 923 through the winding of motor magnet 950 to battery. Motor magnet 950 in a similar manner steps its 70 wipers 954 into engagement with its sixth bank contact terminating the No. 6 conductor in cable 890. In response to the first step of wiper 954 off normal springs 952 close a point in the restoring circuit for register RC. Off normal springs 953 75

also close on the first step of wiper 954 to prepare a circuit for relay 820 in order that the call controller will retransmit the second digit stored at a time when the third digit is being registered. Relay 900 and magnet 920 energize and deenergize in the manner previously described to step the wiper 923 after the third digit into engagement with its fourth bank contact in order to register the fourth digit.

10 In response to the calling subscriber dialling the fourth digit, or digit 7 line relay 730 deenergizes seven times and on each deenergization transmits a ground pulse through relay 900 and motor magnet 960 of switch RD to grounded battery. Motor magnet 960 advances wiper 964 one step in response to each energization to step wiper 964 into engagement with its seventh bank contact terminating the No. 7 conductor in cable 890. In response to the first step of wiper 964 off 15 normal springs 962 close a point in the self-restoring circuit of switch RD and also closes off normal springs 963 so as to cause the controller to retransmit the stored third and fourth digits. After the fourth digit, relay 900 deenergizes and 20 at armature 901 again completes the circuit for energizing magnet 920 to step wiper 923 into engagement with its sixth bank contact. The called number has now been stored on the storing switches RA, RB, RC and RD.

25 30 As soon as wiper 964 takes its first step in response to the second digit dialled by the calling subscriber off normal springs 943 close a circuit for energizing relay 820 to start the "group finding" cycle of operations of the controller. The 35 operation of off normal springs 943 completes a circuit for energizing relay 820 as follows: from ground by way of off normal springs 943, first bank contact engaged by wiper 915 of the sending control switch X, conductor 853, armatures 373 and 341, and through the winding of relay 820 to grounded battery. Relay 820, upon energizing, at armature 821 completes a circuit for energizing slow to release relay 850 as follows: from ground by way of armatures 813 and 831, 40 first bank contact and wiper 886 of counting switch CS and through the winding of relay 850 to grounded battery. At armature 822 relay 820 completes a circuit from grounded armature 813 for energizing the motor magnet 885 of counting 45 50 switch CS which upon energization positions its pawl preparatory to stepping the wipers 886 and 887 since the counting switch is of the indirect drive type. At armature 823 relay 820 prepares a locking circuit for itself and at armature 824 55 connects grounded battery through the winding of relay 820 to negative trunk conductor 252 to energize the line relay 310 in the first group selector as follows: from ground by way of resting contact and armature 321 in Fig. 4, through 60 the lower high resistance winding of line relay 310, armature 323, through the upper low resistance winding of line relay 310, resting contact and armature 331, conductor 252, wiper 277, conductor 257, armature 811 and its resting contact, 65 conductor 784, armature 772, conductor 785, armature 824 and through the winding of marginal relay 830 to grounded battery. Due to the high resistance of the lower winding of line relay 310 marginal relay 830 will not energize over the 70 above traced circuit.

75 Relay 850, upon energizing, at armature 851 prepares a circuit for locking slow to release relay 850 and at armature 852 completes a circuit for energizing motor magnet 910 of the sending control switch X by way of conductor 854.

Motor magnet 910, upon energizing, positions its pawl preparatory to stepping the wipers of the sending control switch and at interrupter springs 911 opens a point in its restoring circuit. Sender control switch X, like counting switch CS as previously stated, is of the indirect drive type in which the wipers are only stepped upon deenergization of the associated motor magnet.

5 In the first group selector shown in Fig. 4 line relay 310, upon energizing over the previously traced circuit, at armature 312 completes a circuit for automatically advancing the wipers of the selector as follows: from ground by way of armature 312, interrupter contact 339 and resting contact, armature 333 and through the 10 winding of motor magnet 338 to grounded battery. Motor magnet 338 positions its pawl preparatory to stepping the wipers of the selector and at its interrupter contacts 339 interrupts the 15 previously traced circuit via motor magnet 338 to cause its deenergization in case wipers 345 or 346 are not in engagement with a grounded group contact. In this case since wiper 345 is normally in engagement with a grounded group bank contact the circuit is completed from this 20 grounded bank contact by way of wiper 345 and armatures 313 and 333 through the winding of 25 motor magnet 338 to maintain the magnet in energized position. A circuit may now be traced for short circuiting the lower high resistance 30 winding of line relay 310 as follows: from ground by way of armature 312, interrupter contacts 339 and its working contact, lower high resistance winding of relay 310, armature 321 and its resting contact to ground. Since the high resistance 35 winding of the relay 310 is short circuited marginal relay 830 in the call controller is energized in series with the lower winding of line relay 310. The operation just described, that is, the 40 change of resistance in the circuit extending to relay 830, occurs each time a grounded group contact is encountered by wipers 345 or 346. Since the grounded bank contact accessible to wipers 345 and 346 designate the different trunk 45 groups as previously described, then this change of resistance in the circuit to the call controller takes place at the start of each trunk group. Marginal relay 830, upon energizing in series with the low resistance winding of line relay 310, at 50 armature 831 completes an obvious circuit for energizing relay 840, and at armature 832 prepares a locking circuit for relay 810. Relay 840, upon energizing, at armature 841 opens the circuit of relay 820 which accordingly deenergizes, and at armature 842 completes a locking circuit 55 for itself from grounded armature 874. Relay 820 deenergizes and at armature 821 momentarily opens the circuit of relay 850 and at armature 822 opens a circuit to the motor magnet 885 of counting switch CS to deenergize the motor magnet 60 to step the wipers of the counting switch 886 and 887 into engagement with their first bank contacts. In this position slow to release relay 850 is maintained energized from the grounded multiply connected bank contacts engaged by 65 wiper 886 of counting switch CS in the second and subsequent positions. At armature 824 relay 820 opens the circuit through line relay 310 in the group selector and to the marginal relay 830 in the call controller, and at armature 825 completes 70 a short circuit around the winding of relay 840 to cause its deenergization. This short circuit may be traced as follows: from the left-hand terminal of relay 840, armature 825, armature 842, to the right-hand terminal of relay 840. 75

- In the first group selector the deenergization of line relay 310 at armature 312 opens the short circuit around the high resistance winding of line relay 310 and at armature 313 opens the circuit 5 maintaining the motor magnet 338 in energized position. The magnet 338 accordingly deenergizes and steps the wipers of the group selector into engagement with the first bank contact in the first group.
- 10 In the call controller the deenergization of relay 830 at armature 831 opens the circuit extending to relay 840. Relay 840 is slow to deenergize since its winding is short circuited at armature 825, and upon fully restoring at armature 841 15 again completes the circuit for energizing relay 820. Relay 820 again energizes and at armature 822 again completes the circuit extending to the motor magnet 885 of the counting switch CS and at armature 824 again connects battery to 20 the winding of marginal relay 830 through both the high and low resistance windings of line relay 310 to again energize the latter relay.
- Line relay 310, upon energizing, at armature 312 25 closes a self-interrupting circuit through motor magnet 338 to automatically advance the wipers of the selector over the contacts in this first group. The closure of armature 313 is effective at this time because wiper 345 does not encounter a grounded group bank contact until the last line 30 in this group is reached. During the self-interrupting operation of motor magnet 338 the make contacts of interrupter spring 339 are not closed for a sufficient time to effectively short the high resistance winding of line relay 310 and therefore 35 fore during this operation relay 830 does not operate. Motor magnet 338, upon each deenergization, continues to advance the wipers of the selector step by step until the wiper 345 engages a grounded group contact, in this case the last 40 trunk in the first group, at which time motor magnet 338 is maintained energized from the grounded group contact by way of wiper 345 and armatures 313 and 333 as previously described. At armature 312 and interrupter springs 339 45 and its working contact the lower high resistance winding of line relay 310 is again shorted to change the resistance in the circuit extending to relay 830 in the call controller to cause relay 830 to again energize and operate the relays in the 50 call controller in the same cycle of operations as previously described. That is, relay 830 energizes and causes the energization of relay 840, as previously described. Relay 840 energizes and causes the release of relay 820. Relay 55 840, upon deenergizing, causes the counting switch CS to take another step and opens the circuit to relays 310 and 830. The deenergization of line relay 310 in the group selector steps the wipers of the selector to the first contact in the second 60 group. Relays 830 and 840 deenergize and relay 820 reenergizes as before. Relay 820, upon reenergizing, again completes the circuit for energizing line relay 310 by way of armature 824 to again cause the automatic stepping of the wipers 65 of the selector to the last trunk in the second group. From the foregoing it will be seen that at this time group wiper 345 engages a bank contact designating another group, the resistance of the circuit between the call controller and the 70 selector is changed to cause the cycle of relay operations just described to take place and to cause the counting switch CS in the call controller to advance one step.
- Since the digit 4 is stored in the storing switch 75 or register RA, four cycles of relay operations

take place and counting switch CS takes four steps at which time wiper 887 encounters the grounded conductor No. 4 included in cable 899—said ground extending by way of wiper 914 of the sending control switch S, wiper 934 of the first 5 storing switch RA in engagement with its fourth bank contact terminating No. 4 conductor included in cable 890, through the fourth bank contact engaged by wiper 881 of the counting switch CS and through the winding of slow to release 10 relay 860 to grounded battery for energizing the latter relay. Relay 860, upon energizing, at armature 861 closes a self-restoring circuit for the counting switch CS; at armature 862 completes a locking circuit for itself from armature 851 and 15 at armature 863 completes a circuit for energizing relay 810. Relay 810, upon energizing, at armature 811 connects ground at armature 771 to the negative conductor 252 by way of conductors 783 and 278; at armature 812 prepares a circuit 20 for connecting negative battery through the winding of marginal relay 830 to the positive line conductor 258 by way of conductors 785, 784 and 286 when relay 820 is later on energized; at armature 813 disconnects ground to prevent the 25 premature energization of motor magnet 885 and relay 850; at armature 814 prepares a locking circuit for relay 820; at armature 815 disconnects ground from conductor 793 to open the circuit extending through the lower winding of relay 740; 30 at armature 816 prepares a locking circuit for itself and at armature 817 opens a point in the restoring circuit for the sending control switch S. Relay 820 reenergizes when relay 840 deenergizes and at armature 824 connects negative battery through the winding of relay 830 to conductor 258 to cause energization of relay 320 in the group selector through its second step to start the "trunk finding" cycle of operations of the first group selector. The circuit for energizing relay 320 in 40 the group selector in series with relay 830 in the call controller may be traced as follows: from ground by way of off normal springs 315, which close on the first step of the wipers of the selector, by way of the lower winding of two-step relay 320 45 through the normally closed springs controlled by armature 334, conductor 253, wiper 276, conductor 286, armature 812 and its working contact, conductor 784, armature 772, conductor 785, armature 824, and through the winding of relay 50 830 to battery. The closure of armatures 821 and 822 by operation of relay 820 is ineffective at this time because armature 813 is operated. At armature 823 relay 820 completes a locking circuit for itself from grounded armature 814. 55

A circuit for restoring the counting switch CS to normal may be traced as follows: from ground by way of the multiple contacts engaged by wiper 886, armature 861, interrupter springs 884, through the winding of magnet 885 to 60 grounded battery. Motor magnet 885 energizes and deenergizes in the manner of a buzzer to advance the wipers of the counting switch until wiper 886 no longer encounters a grounded bank contact at which time wiper 886 will come into 65 engagement with its normal position bank contact. When the counting switch wiper reaches the position shown in the drawings, or its normal position, the circuit through the winding of slow to release relay 850 is opened with the result that 70 this relay deenergizes after an interval. At armature 851 relay 850 opens the locking circuit to relay 860 which deenergizes after an interval, and at armature 852 opens the circuit extending to motor magnet 910 of the sending control 75

switch X. Motor magnet 910 deenergizes and steps the wipers 913 to 915, inclusive, one step into engagement with their second bank contacts in order to control the retransmission of the second digit stored in the second register RB. Relay 860, being slow to release, deenergizes after an interval and at armature 861 opens a point in the previously traced restoring circuit for the counting switch CS; at armature 862 opens a point in its own locking circuit, and at armature 863 opens the original energizing circuit of relay 810, which latter relay is held energized by way of armature 816 and armature 832 of relay 830 is still in energized position. The "trunk finding" cycle will normally be completed by the time relay 860 releases and is indicated by relay 830 being in its deenergized position. At this time sending control switch X will be in second position and relay 820 cannot reoperate until the third digit is being stored on the register switch RC in response to the calling subscriber dialling the third digit.

Returning now to the first group selector, a slight review of its operation will first be given up to the time of the start of the trunk finding cycle. The operation of line relay 310 closes a circuit to operate the motor magnet 338 in its self interrupting circuit until wiper 345 or wiper 346 engages a grounded group contact indicating the beginning of a group of trunks. This grounded bank contact holds the motor magnet 338 in energized position and shunts the high resistance winding of relay 310, thereby causing a relay cycle operation in the controller with the result that battery will be momentarily removed from the negative talking conductor 252. This disconnection of battery from conductor 252 causes the deenergization of line relay 310 which in turn causes the deenergization of the motor magnet 338, thereby stepping the wipers of the selector to the first contact in the group. After a short interval line relay 310 is reenergized by the controller in its cycle operation reconnecting battery to negative trunk conductor 252. This reenergizes line relay 310, thereby completing a circuit for operating motor magnet 338 which interrupts itself in the same manner to advance the wipers step by step until wiper 345 or wiper 346 again encounters a grounded group bank contact indicating a succeeding group of trunks. This group selecting cycle of operations continues in this manner until the called group is reached, at which time the controller connects negative battery to the positive conductor 258 to operate two-step relay 320 in its second step. In this case, since the first digit dialled is 4 the wipers of the selector are operated through four cycles of group selecting operations with the wipers resting on the last trunk of the third group and at this time negative battery is connected to conductor 258 to energize relay 320 in its second step to start the trunk finding operation.

Relay 320, upon energizing, through its second step, at armature 322 connects ground at armature 311 through the lower winding of trunk test relay 330 to the test wipers 343 and 344; at armature 323 opens the circuit extending through the upper winding of line relay 310; at armature 325 completes a self interrupting circuit by way of interrupter springs 339 and armature 333 to the motor magnet 338; and at armature 326 connects the group wipers 345 and 346 by way of armature 333 to the winding of the motor magnet 338. Motor magnet 338 intermittently operates and advances the wipers of the selector step by step in search of an idle trunk. As soon as test wiper

343 encounters an idle trunk in this group, indicated by presence of negative battery on the engaged test bank contact, relay 330 energizes over the following circuit: from ground by way of armature 311, armature 322, through the lower winding of test relay 330, test wiper 343 in engagement with the bank contact terminating the idle trunk in this group, conductor 356, and through the upper winding of the two-step relay and test relay in the second selector, corresponding to relays 320 and 330 in the first group selector. Relay 330 at armature 331 connects the negative talking conductor 252 by way of wiper 341 to negative talking conductor 352 extending to the second selector, at armature 332 disconnects the upper winding of two-step relay 320 and connects the control lead 256 by way of wiper 343 to control lead 256 thereby completing a circuit for operating the two-step relay in the second group selector to operate its armature 324 in its first step; at armature 333 opens the circuit to motor magnet 338 to stop the wipers of the selector on the idle trunk; and at armature 334 disconnects the lower winding of two-step relay 320 from conductor 258 thereby opening the circuit to relay 830 in the call controller and connects positive talking conductor 258 by way of wiper 347 to conductor 358.

It will be remembered that the second group selector is identical to the first group selector and therefore negative talking conductor 352 is connected to grounded battery through both windings of the line relay in the second selector while the positive talking conductor 358 is open since the off normal springs in the second group selector, similar to springs 315 and 316 are not yet operated. Ground on control conductor 256 extending from armature 718 in the call controller operates the two-step relay corresponding to relay 320 in the second selector in its first step to open the second selector restoring circuit.

In the call controller relay 830 deenergizes in response to the operation of test relay 330 in the first selector and at armature 632 opens the locking circuit to relay 810. Relay 810 deenergizes in case relay 830 is deenergized at this time. In response to the deenergization of relay 810 said relay at armatures 811 and 812 connects negative battery and ground to conductors 352 and 358 by way of wipers 341 and 347 of the first selector. The line relay in the second selector is energized in series with relay 830 in the call controller. At armature 813 relay 810 again energizes relay 850 over the first contact and wiper 886 and again at armature 813 energizes the motor magnet 885 of the counting switch CS. At armature 814 relay 810 opens the locking circuit of relay 820, but relay 820 is held energized over armatures 841 and 873, conductor 853, wiper 915, in engagement with its second bank contact, off normal springs 953 to ground in case the third digit has been dialled; and at armature 815 reconnects ground to conductor 793 to again energize relay 740 to maintain the slow release arrangement in its operated position. Relay 850 again energizes and at armature 852 again energizes motor magnet 910 preparatory to stepping the wipers of the sending control switch X.

The energization of the line relay in the second selector causes the operation of the motor magnet therein to step the wipers of the second selector into engagement with the first grounded group bank contact at which time the high resistance winding of the line relay is short circuited to

cause the operation of relay 830 in a manner similar to that previously described. Relay 830, upon energizing, causes relay 840 to energize and this latter relay in turn causes the deenergization of relay 820. Relay 820, upon deenergizing, causes the counting switch CS to take one step. As soon as wiper 886 engages the grounded multiple bank contacts maintain relay 850 energized. At armature 824 relay 820 opens the circuit to relay 830 and to the line relay in the second selector. The line relay in the second selector deenergizes and causes the motor magnet therein to advance the wipers into engagement with the bank contacts terminating the first trunk in the first group.

15 In the call controller relays 830 and 840 again deenergize and the deenergization of relay 840 again causes the reenergization of relay 820. At armature 824 relay 820 again completes the circuit for energizing the line relay of the second selector in series with relay 830. The line relay, upon energizing, causes the motor magnet to step the wipers over the bank contacts in the first group to the second group of trunks at which time the high resistance winding of the line relay is shorted when the next group bank contact is encountered to cause the energization of relay 830 as previously described. In the same manner as previously described relays 830 and 840 energize—relay 820 deenergizes to step the counting switch CS and to deenergize the line relay of the second selector and relays 830 and 840. This group finding cycle of operations continues until wiper 887 of the counting switch CS encounters the conductor grounded by the second storing switch RB, in this case conductor 5, since the digit 5 is stored in switch RB. At this time the line relay in the second selector energizes and steps the wipers into engagement with the first trunk in the fifth group to start the trunk finding operation. Relays 360 and 810 again energize as previously described and relay 860 restores the counting switch CS. Relay 810, upon energizing, locks the relay 820 energized and reverses the battery connection to the second selector to energize 45 the two-step relay therein in series with relay 830 in a manner similar to that described for the first selector. In a similar manner the two-step relay in the second selector causes the wipers to be automatically stepped in search of an idle trunk 50 in the group and when such trunk is encountered the test relay therein, similar to test relay 330, energizes and connects the call controller to conductors 362, 366 and 368 terminating in the connector shown in Fig. 5.

55 The energization of the test relay in the second selector opens the circuit to relay 830 in the call controller with the result that relay 830 deenergizes. When the counting switch CS reaches its normal position relay 850 deenergizes to open the locking circuit of relay 860 at armature 851 and at armature 852 opens the circuit to motor magnet 910 to cause the motor magnet to deenergize and step the wipers 913 to 915 of the sending control switch X into engagement with their bank contacts. After an interval relay 860 deenergizes and opens the circuit to relay 810 at armature 863. Relay 810 deenergizes when both relays 860 and 830 are deenergized, it being remembered that relay 830 deenergizes in response 65 to the selector switching through on the idle trunk.

At armatures 811 and 812 relay 810 reconnects battery and ground to conductors 252 and 258 which are now connected by way of the selector 70 wipers to conductors 362 and 368. At armature

813 relay 810 reenergizes relay 850 by way of wiper 886 and reenergizes motor magnet 885 by way of armature 822. At armature 814 relay 810 opens the locking circuit to relay 820 but this relay is maintained energized from ground extending by way of off normal springs 963, wiper 915, conductor 853, and armatures 873 and 841. At armature 815 relay 810 reconnects ground to reenergize relay 740 to restart the timing relay arrangement. Relay 850, upon reenergizing, at 10 armature 852 against reenergizes motor magnet 910 preparatory to stepping the wipers of the sending control switch X.

A circuit for energizing the line relay 410 of the connector in Fig. 5 may now be traced as follows: 15 from ground through the lower high resistance winding, through the upper low resistance winding of relay 410, armatures 441 and 451, conductor 362, through the bank contact and wiper of the second group selector to conductor 352, 20 bank contact and wiper 341 of the first group selector in Fig. 4, working contact and armature 331, conductor 252, wiper 277, conductor 287, armature 811 and resting contact, conductor 784, armature 772, conductor 785, armature 824 and 25 through the winding of marginal relay 830 to grounded battery. Due to the high resistance winding of line relay 410 relay 839 is not energized in series therewith. Release relay 460 in the connector is energized over the control lead as follows: 30 ground by way of armature 778, armature 751, conductor 285, wipers 275, conductor 256, armature 332 and working contact, wiper 343, conductor 356, through the wiper and bank contact of the second selector to conductor 366, 35 through normally closed off normal springs 467, and through the winding of relay 416 to battery. At armature 461 relay 460 prepares a locking circuit for relay 450; at armature 462 prepares a circuit for change-over relay 430; at armature 40 463 prepares the locking circuit for test relay 440; at armature 464 locks up to grounded control conductor 366 independent of off normal springs 467; and at armature 465 prepares a point in the ringing circuit. Line relay 410, upon energizing, 45 at armature 411 completes a circuit for energizing the motor magnet 415; and at armature 412 prepares a self interrupting circuit for motor magnet 415 and a point in the circuit for shunting the high resistance winding of line relay 410. 50 The circuit for energizing motor magnet 415 may be traced as follows: from the grounded group bank contact normally engaged by wiper 475, armature 411, resting contact and armature 425 and through the winding of motor magnet 415 to 55 grounded battery. Motor magnet 415 energizes and positions its pawl preparatory to stepping the wipers of the connector and closes its interrupter springs 416 to shunt the lower high resistance winding of line relay 410 as follows: 60 from ground by way of armature 412, interrupter springs 416 and their working contacts and thence through the lower winding of line relay 410 to ground.

Relay 830 in the call controller energizes in 65 response to the change in resistance over lead 362 when the high resistance winding of line relay 410 is shunted. At armature 831 relay 830 again completes the circuit for energizing relay 840 and the latter relay at 841 opens the circuit of relay 70 820 which thereupon deenergizes. At armature 822 relay 820 opens the circuit to motor magnet 885 of the counting switch CS to deenergize such magnet to step the wipers of the counting switch into engagement with their first bank contacts; 75

at armature 824 opens the circuit to line relay 410 and relay 830, and at armature 825 short circuits relay 840. In the connector the deenergization of line relay 410 opens the circuit to motor magnet 415 with the result that the wipers 471, 473, 475 and 477 are advanced one step into engagement with their second bank contacts. In the call controller relays 830 and 840 deenergize as previously described. At armature 841 relay 840 completes the circuit from grounded off normal springs 963, third bank contact and wiper 915 of counting control switch S, conductor 853, armatures 873 and 841 through the winding of relay 820 to battery. Since these operations are similar to those previously described for the first group selector, the detailed circuits for each relay operation is therefore not traced in full at this time. Relay 820 at armature 824 again connects grounded battery through the winding of relay 830 to the negative conductor 362 for again energizing line relay 410 in the connector. A self interrupting circuit is now completed from ground at armature 412 by way of interrupter spring 416 and its resting contact through the winding of motor magnet 415 to grounded battery, with the result that the wipers of the connector are advanced automatically step by step until wiper 475 engages its eleventh bank contact which is the last line in the first group. When wiper 475 engages its eleventh bank contact which is grounded to designate the end of the first group and start of the second group a circuit is completed from the grounded bank contact by way of wipers 475, armature 411, resting contact and armature 425 and through the winding of motor magnet 415 to grounded battery for maintaining magnet 415 in energized position. At interrupter springs 416 and their working contact the high resistance winding of line relay 410 is again short circuited to cause the energization of the marginal relay 830 in the call controller in a manner similar to that previously described. Relays 830 and 840 energize, relay 820 deenergizes to short circuit relay 840 and to step the counting switch CS into engagement with its second set of bank contacts and to open the circuit to line relay 410 and relay 830.

In the connector, line relay 410, upon deenergizing, at armature 411 opens the locking circuit of motor magnet 415 whereupon the magnet deenergizes and advances the wipers of the connector into engagement with the first bank contact in the second group. In the call controller relays 830 and 840 deenergize and relay 820 again energizes by way of armature 841. Relay 820 again connects grounded battery through relay 830 in series with line relay 410, whereupon line relay 410 energizes and at armature 412 completes the self-interrupting circuit of motor magnet 415 to cause the wipers of the connector to be automatically stepped until wiper 475 again encounters a grounded group bank contact. When group wiper 476 engages the third grounded group bank contact in this case the twenty-first bank contact magnet 415 is locked energized in the manner previously described. Magnet 415 at armature 416 again shunts the high resistance winding of line relay 410 to energize marginal relay 830 in the call controller. Relays 830 and 840 again energize and relay 820 deenergizes to short circuit relay 840 and step the wipers of the counting switch CS to its third position. At armature 824 relay 820 again opens the circuit of relays 410 and 830. Relays 830 and 840 deenergize and the same cycle of operations

is repeated until the registered digit, in this case digit 6, is found by the counting switch CS.

When wiper 887 of the counting switch encounters the conductor terminating the registered digit 2 circuit for energizing relay 860 may be traced as follows: from ground by way of wiper 914 of sending control switch X in engagement with its third bank contact, wiper 954 of the third storing or register switch RC in engagement with the bank contact terminating the No. 10 conductor included in cable 1890, the bank contact terminating conductor 6 and wiper 887 of the counting switch CS and through the winding of relay 860 to battery. Just before double ended wiper 475 again engages its front grounded bank contact the wipers 471, 473 and 477 are in engagement with their last bank contact and on the next step of the wipers, wipers 471, 473 and 477 disengage from their bank contacts while wipers 472, 474 and 478 now engage their first bank contacts. The last mentioned wipers are now in engagement with the last line in the fifth group while wiper 475 engages the first grounded group bank contact to again maintain the motor magnet 415 energized to cause the high resistance of relay 410 to be short circuited. As previously described this results in the energization of relay 830, the energization of relay 840, and the deenergization of relay 820 to cause the deenergization of relay 410 and relay 830. The deenergization of line relay 410 at this time advances wipers 472, 474, 475 and 478 into engagement with their second bank contacts, which in this case is a set of dead contacts. Relay 860, upon energizing, at armature 861 again completes the restoring circuit for the counting switch CS to restore its wipers to normal, as previously described; at armature 862 completes a locking circuit for itself; and at armature 863 completes the circuit for energizing relay 810. At armature 811 relay 810 connects ground at armature 771 to the negative talking conductor 362; at armature 812 prepares a circuit for connecting battery through the winding of marginal relay 830 to positive talking conductor 368, at armature 814 prepares the locking circuit for relay 820; at armature 815 opens the circuit to relay 740 to initiate the operation of the slow releasing device, and at armature 816 prepares a locking circuit for itself. Relay 820 again energizes over its previously traced circuit and at armature 823 completes its locking circuit. At armature 824 relay 820 completes a circuit for energizing change-over relay 430 in series with relay 830 as follows: from ground by way of off normal springs 486 which closed on the first step of the connector wipers, armature 453 and resting contact, armature 462 and working contact, armature 446, the upper high resistance winding of relay 430, the lower low resistance winding of relay 430, resting contact and armature 455, conductor 368, through the bank contact and wiper of the second group selector to conductor 358, wiper 347, armature 334 and its working contact, conductor 258, wiper 276, conductor 286, armature 812 and its working contact, conductor 784, armature 772, conductor 785, armature 824, and through the winding of marginal relay 830 to grounded battery. Due to the high resistance in the upper winding of change-over relay 430 marginal relay 830 is not energized in series therewith. At armature 431 relay 430 operates two-step relay 420 in its first step to close only armature 422 by way of armature 424 and resting contact and the lower winding of two step relay 420; 75

Two-step relay 420 closes only armature 422 because its upper winding is short circuited at this time over the following path: from ground by way of armature 431, armature 424 and resting contact, the upper winding of relay 420, armature 422, working contact and armature 462, resting contact and armature 453, and through off normal springs 468 to ground.

In the call controller when the counting switch 10 is restored to normal relays 850, 860 and 810 deenergize in the same manner as previously described. At armatures 811 and 812 relay 810, upon deenergizing, reverses the battery and ground connections to talking conductors 362 and 15 368 of the connector switch thereby opening the circuit of change-over relay 430 which accordingly deenergizes. At armature 814 relay 810 opens the locking circuit of relay 820 and the latter relay thereupon deenergizes to open the 20 circuit to motor magnet 885 at armature 822 to step the wipers of the counting switch CS into engagement with their first bank contacts whereupon relay 850 is maintained energized by way of wiper 886 as previously described.

25 When relay 430 in the connector deenergizes said relay at armature 431 removes the short circuit from around the upper winding of two-step relay 420, thereby completing the circuit through both windings of this relay in series to ground at off normal springs 468 for energizing relay 430 in its second step. At armature 421 relay 420 prepares a point in the ringing circuit, at armature 423 closes a short circuit around the upper high resistance winding of change-over 30 relay 430, at armature 424 prepares the test circuit through the lower winding of test relay 440, at armature 425 prepares an operating circuit for motor magnet 415, and at armature 426 prepares the generator return circuit. When relay 40 820 energizes after the deenergization of relay 840 line relay 410 in the connector is again connected in series with marginal relay 830 by way of armature 824 whereupon the line relay 410 energizes and at armature 412 completes a circuit by way 45 of armature 425 for energizing motor magnet 415 of the connector. Motor magnet 415 energizes and positions its pawl preparatory to stepping the wipers of the connector and at its interrupter springs 416 and its working contact completes a circuit for short circuiting the lower high resistance winding of line relay 410 from 50 grounded armature 412, interrupter springs 416 and working contact, to the lower winding of relay 410.

55 Relay 830 in the call controller energizes as a result of the short circuiting of the high resistance winding of relay 410 and at armature 831 again completes the circuit for energizing relay 840. At armature 831 relay 840 opens the circuit 60 of relay 820 which accordingly deenergizes. Relay 820 deenergizes and at armature 822 steps the counting switch CS to its second bank contact, at armature 824 opens the circuit of both relays 830 and 840 and at armature 825 again short circuits relay 840. The connector line relay 410 again deenergizes and at armature 412 opens the circuit to motor magnet 415 which accordingly deenergizes and steps the wipers of the connector into engagement with the first line in 65 the sixth group. In the call controller relays 830 and 840 deenergize. At armature 841 relay 840 again completes the circuit for energizing relay 820; at armature 822 relay 820 again energizes motor magnet 885, at armature 825 opens 70 the shunt around relay 840, and at armature 824 reoperates line relay 410 in series with relay 830. In the connector, line relay 410, upon energizing, at armature 412 again energizes motor magnet 415. Motor magnet 415 prepares to step the wipers of the connector and at spring 416 and its 5 working contact again completes the shunt circuit around the high resistance winding of line relay 410 to energize marginal relay 830 in the call controller. In the call controller relays 830 and 840 reenergize and relay 820 deenergizes to 10 open the circuit of line relay 410 and relay 830 at armature 824, the shunt relay 840 at armature 825, and to operate the counting switch CS to its third position from armature 822, as previously described. In the connector switch the deenergization of line relay 410 at armature 412 opens the circuit to motor magnet 415 which accordingly deenergizes and steps the wipers of the connector into engagement with the second line in the sixth group. In the call controller relays 830 and 840 deenergize and relay 820 again energizes. The energization of relay 820 restarts the same cycle of operations as just described and this continues until relay 860 in the call controller is energized over wiper 887 in response to the counting switch CS engaging conductor No. 7 in cable 25 890 which has been grounded by the storing or register switch RD in response to being set by the calling subscriber dialling the digit 7. The circuit for energizing relay 860 may be traced as follows: from ground by way of wiper 914 of the sender control switch S in engagement with its fourth bank contact, wiper 964 of the register switch RD in engagement with the bank contact of their No. 7 conductor included in cable 890, 30 the seventh bank contact in counting switch CS terminating the No. 7 conductor, wiper 887 and through the winding of relay 860 to grounded battery. At armature 861 relay 860 again closes the restoring circuit of the counting switch CS 40 to restore the switch to its normal position or the position shown in the drawings, at armature 862 completes a locking circuit for itself, and at armature 863 reenergizes relay 810. Relay 810 at armature 814 locks relay 820, at armature 815 opens the circuit of relay 740 to restart the slow 45 acting device, at armature 816 completes its own locking circuit, and at armatures 811 and 812 opens the circuit to line relay 410 and relay 830. The deenergization of relay 410 causes motor 50 magnet 415 to deenergize and advance the wipers of the connector into engagement with the seventh line of the sixth group, in this case the particular line being called. In addition, the operation of armature 812 also closes a circuit for 55 energizing relays 830 in series with relay 430 as follows: from ground by way of operated off-normal springs 468, armature 453 and resting contact, armature 462 and working contact, armature 446, armature 423, through the lower low 60 resistance winding of change-over relay 430, resting contact and armature 455, conductor 368 over the previously traced circuit including conductors 358, 258, 286, 784, and 785 through the winding of marginal relay 830 to battery. At armature 65 831 relay 830 again operates relay 840 and at armature 832 completes a locking circuit for relay 810. Relay 840 energizes but at this time does not cause the deenergization of relay 820 because the same is held locked in energized position by way of armatures 814 and 823.

In the connector change-over relay 430 energizes and at armature 431 completes the circuit by way of armature 424 through the lower winding of test relay 440 to test wiper 474 in engage- 70 75

ment with the test conductor terminating the called subscriber's line. In case the called subscriber's line is idle, then this conductor will have battery potential connected thereto through the winding of the cut-off relay in the associated line circuit, and through the armature similar to armature 22 and resistance to negative battery. In case the called line is idle then test relay 449 energizes from the battery potential on the test conductor. At armature 441 relay 440 disconnects line relay 410 from the negative talking conductor 362, at armatures 442 and 445 completes the ringing circuit; at armature 446 disconnects ground from the winding of relay 430 the same as relay 830 in the call controller; at armature 443 completes a locking circuit for itself from grounded armature 463 through its upper winding; and at armature 444 grounds wipers 473 and 474 to busy the called line and to operate the bridge cut-off relay similar to bridge cut-off relay 20 in the line circuit. The bridge cut-off relay in the called line circuit operates and disconnects the line relay thereof and ground from the line conductors of the called line.

25. In the call controller relay 830 deenergizes and at armature 832 unlocks relay 810 in case the counting switch is restored and relay 860 deenergizes. Relays 860 and 850 and relays 810 and 820 deenergize as previously described. The deenergization of relay 850 at armature 852 opens the circuit of motor magnet 910 whereupon the wipers of the sender control switch S are stepped into engagement with their fifth bank contacts. In this position a circuit may be traced from 35 grounded wiper 914 by way of conductor 795, armature 757, conductor 796, armature 817, when relay 810 is deenergized, conductor 856, interrupter springs 911, and through the winding of motor magnet 910 to grounded battery for energizing motor magnet 910 to advance the wipers of the sending control switch into engagement with their sixth bank contacts. As soon as wiper 40 913 of the sending control switch leaves its fifth bank contact the circuit extending by way of the multiple bank contacts and conductor 792 to the controller release relay 720 is opened whereupon relay 720 deenergizes after an interval, in order to release the call controller. When wiper 913 of the sending control switch X reaches 45 its sixth position a circuit is completed for energizing relay 210 in the secondary trunk relay group as follows: from grounded wiper 913 in engagement with its sixth bank contact, conductor 786, armature 774, conductor 284, wiper 274, through the winding of relay 210 to grounded battery. Relay 210, upon energizing, at armatures 211, 212, 215 and 216 connects the calling line to the called line over the heavy talking conductors. At armatures 213 and 214 relay 50 210 grounds the control leads 156 and 256 to maintain the connection and to hold energized the test relays 330 and relay 460. Line relay 220 in the secondary trunk relay group is now energized over the calling subscriber's loop as follows: from ground through the lower winding of relay 220, armature 215, conductors 158, wiper 157, conductor 117, wiper 107, conductor 2, through the calling substation loop to conductor 1, wiper 101, conductor 111, wiper 151, conductor 152, armature 55 212 and through the upper winding of line relay 220 to grounded battery. Talking battery is therefore supplied to the calling subscriber through the two windings of the line relay 220. At armature 221 relay 220 connects up the ring 60 back tone by way of armatures 241 and 221

through the condenser C and from thence over the previously traced circuit to the calling subscriber's line. At armature 222 relay 220 completes an obvious locking circuit for relay 210 to maintain relay 210 in energized position independent of the call controller. 5

In the connector the ringing circuit for ringing the called subscriber is completed by the operation of test relay 440 as follows: from generator, through the lower winding of relay 450, armatures 442 and 421, wiper 472, bank contact 61 of the called line, conductor 51, through the line circuit and substation ringer of the called line to conductor 52, bank contact 67, wiper 478, armature 426, working contact and armature 456 to 10 armature 445 and ground. When the called subscriber answers relay 450 is energized over the called subscriber's loop as previously traced, and at armature 454 completes a locking circuit for itself from grounded armature 461 through its 15 upper winding. At armatures 451 and 455 relay 450 completes the talking circuit between the calling and called subscribers' lines over the heavy talking conductors, at armature 453 opens the circuit to two-step relay which accordingly deenergizes and at its working contact connects ground by way of off normal springs 468 to the upper winding of test relay 440 to maintain this relay in energized position during the restoration of the switch wipers to their normal position. 25 Two-step relay 420, upon deenergizing, at armatures 421 and 426 opens the ringing circuit, at armature 423 opens the short circuit from around the upper winding of relay 430, and at armature 424 opens the original energizing circuit of test 30 relay 440. In response to the called subscriber answering back bridge relay energizes after the energization of the ring cut-off relay 450 over the following circuit. From ground through the lower winding of relay 230, armature 216, conductor 258, armature 334 and working contact, wiper 347, conductor 358, positive line wiper of the second group selector to conductor 368, armature 455 and working contact, wiper 478, bank contact 61, conductor 52, through the called 35 substation loop to conductor 51, bank contact 67, wiper 472, working contact and armature 451, conductor 362, bank contact and negative line wiper of the second group selector, conductor 352, wiper 341, working contact and armature 331, 40 conductor 252, armature 211 and through the upper winding of relay 230 to grounded battery. Talking battery to the called line therefore is furnished through the upper and lower windings of back bridge relay 230. At armature 231 relay 45 230 completes the circuit for energizing 240. Relay 240 at armature 241 disconnects the ring back tone; at armature 242 connects ground to the meter conductor 154 to operate the calling subscriber's meter by way of wipers 153 and 103, 50 and at armature 342 locks itself to grounded conductor 256 as well as supplying ground thereto by way of armature 231.

The connection to the called line is now complete, the calling and called subscribers may converse over the heavy talking conductors, and the call controller will be released in response to the deenergization of relay 720 in a manner to be described hereinafter. 65

Busy condition

It will now be assumed that either the first or a second selector encounters an all trunk busy condition in the selected group. At this time it will be remembered that relays 810, 820, 830, 850 70 75

and 869 in the call controller are energized. If no trunk is available in the selected group, then wiper 345 or wiper 346 will encounter a grounded group contact on the last trunk position in this group. If the last trunk in this group is idle then test relay 330 operates so much faster than motor magnet 338 that the encountered grounded group bank contact will have no effect. However, if this last trunk is busy the engaged grounded bank contact will short circuit the test relay 330 as follows: from ground encountered on the bank contact of the test lead of the last trunk line in this group, wiper 343, lower winding of test relay 330, and by way of armatures 322 and 311 to ground. Since test relay 330 does not energize then motor magnet 338 has sufficient time to energize over the following circuit: from ground by way of the grounded group bank contact, wiper 345, armature 326, armature 333, and through 20 the winding of motor magnet 338 to battery. At interrupter spring 339 and its working contact motor magnet 338 completes a circuit for energizing line relay 310 as follows: from ground by way of armature 325, interrupter spring 339 and working contact, lower high resistance winding of line relay 310, armature 321 and working contact, resistance 327 to grounded battery. At armature 311 relay 310 opens the circuit of test relay 330. Under this busy condition the relay 830 in the call 30 controller is maintained energized in series with two-step 328 and therefore relay 830 at armature 832 maintains relay 810 in energized position. Relay 810 at armature 815 therefore holds open the circuit of relay 740 with the result that said 35 relay deenergizes and the weighted armature 741 vibrates for approximately four seconds after which the circuit to slew release relay 750 is opened. After an interval slow to release relay 750 deenergizes and at armature 751 disconnects ground from conductor 265 and control conductor 256. At armature 753 relay 750 connects the busy by way of resting contact of armature 753, armature 761, tone condenser TC, armature 703, conductor 622, wiper 616, conductor 1 and thence 40 through the calling substation loop. At armature 754 relay 750 opens the circuit to relay 770 which thereupon deenergizes; at armature 755 opens a point in its own locking circuit, and at armature 756 opens the shunt around armature 50 763. Relay 770, upon deenergizing, at armature 771 disconnects ground from conductor 252, at armature 772 disconnects battery through the winding of relay 830 from talking conductor 258 to release relay 329 and relay 830; at armature 55 775 disconnects the common spark quenching condenser and resistance 729; at armature 776 opens a circuit to relay 780, at armature 777 opens the original energizing circuit to relay 780, and at armature 778 disconnects direct ground 60 from armature 751.

Relay 320, upon deenergizing, at armature 321 opens the circuit to line relay 310 which accordingly deenergizes; at armature 322 opens a point in the circuit to relay 330 to prevent the operation of this relay during the restoration of the wipers; and at armature 324 completes the circuit for restoring the switch wipers to their normal position. The circuit for restoring the switch wipers to their normal position may be traced 65 as follows: from ground at off normal springs 316, armature 324, interrupter spring 339 and resting contact, armature 333, and through the winding of motor magnet 338 to grounded battery. Motor magnet 338 energizes and deenergizes in the manner of a buzzer over the above traced cir- 70

cuit to advance the wipers step by step until the off normal springs 315 and 316 are opened at a time when the wipers reach their normal position.

When the calling subscriber hears the busy tone such subscriber will replace his receiver thereby 5 opening the circuit to line relay 730 in the call controller. At armature 731 relay 730 opens the circuit of slow to release relay 760 which deenergizes after an interval. At armature 761 relay 760 disconnects the busy tone; at armature 763 10 opens the circuit to slow to release relay 720, at armature 764 opens a point in the circuit to relay 740, at armature 765 opens the circuit to register switch restoring relay 870 and at armature 766 opens the circuit to motor magnet 920 of the 15 sequence switch SS. Relay 870 deenergizes and completes a circuit for restoring all of the switches in the call controller to normal position. At armature 871 relay 870 disconnects the A. C. source from the primary winding of transformer T and 20 at armature 872 closes the restoring circuit for counting switch CS as follows: from ground through the winding of relay 880, armature 872, off normal springs 883, interrupter springs 884 and through the winding of motor magnet 885 to 25 grounded battery. Motor magnet 885 operates in the manner of a buzzer to advance the wipers of the counting switch until they reach their normal position in which position the restoring circuit is opened at the off normal springs 883 when 30 the wipers reach their normal position. At armature 873 relay 870 opens the original energizing circuit of relay 820, at armature 874 opens the locking circuit for relay 840 which according- 35 ly deenergizes, and at armature 875 closes the re- 35 storing circuit for the sending control switch X as follows: from ground by way of winding of relay 880, armature 875, conductor 885, through the off normal springs 912, interrupter spring 911 and through the winding of motor magnet 910 to 40 grounded battery. Motor magnet 910 operates in the manner of a buzzer over this circuit and advances the wipers of the sending control switch X until the wipers restore to their normal position in which position the off normal springs 912 45 open. At armature 876 relay 870 completes the restoring circuit for sequence switch SS as follows: from ground through the winding of relay 880, armature 876, conductor 857, off normal springs 922, interrupter springs 921, and through 50 the winding of motor magnet 920 to grounded battery. Motor magnet 920 operates in the manner of a buzzer to advance the wiper 923 step by step until the wiper reaches its normal position in which position the off normal springs 922 are 55 opened. At armature 877 relay 870 completes the restoring circuit for the first register or storing switch RA as follows: from ground through the winding of relay 880, armature 877, conductor 858, through the off normal springs 932, in- 60 terrupter springs 931 and through the winding of motor magnet 930 to grounded battery. In a similar manner the restoring circuits for registers or storing switches RB, RC and RD are completed by way of armatures 878, 879 and 882, 65 and their respective off normal springs 942, 952 and 962 to their respective motor magnets 940, 950 and 960 to restore the wipers of the registers or storing switches to their normal positions in which positions the off normal springs open the 70 restoring circuit thereby maintaining the wipers in their normal positions. Relay 880 energizes in series with the respective motor magnets of the switches and at armature 881 grounds conductor 629 to maintain the combination call con- 75

troller busy to the alotted having access thereto.

- Slow to release relay 720 deenergizes shortly after its circuit is opened by relay 760 and at armature 721 opens a point in the circuit of motor magnet 618 and at armature 722 opens the holding circuit to relays 700 and 710 which accordingly deenergize. Relay 710, upon deenergizing, at armature 711 opens another point in the circuit to motor magnet 618, at armature 712 opens a point in the original energizing circuit of relay 700 and disconnects ground from conductor 115 to release the cut-off relay 20 in the calling line circuit, at armature 713 opens a point in the stepping circuit to motor magnet 118; at armature 714 opens the spark quenching circuit; at armature 715 prepares a circuit to relay 740 and at armature 716 disconnects ground from conductor 629 so that this combination call controller may again be used in case the switches are now restored and ground is removed from busy test conductor 629 at armature 881.

When the counting switch CS reaches normal position relay 850 deenergizes and at armature 651 opens the locking circuit of relay 860 which 25 relay 854 deenergizes. At armature 852 relay 854 opens a circuit through motor magnet 910 to allow the sending control switch X to restore to its normal position as previously described. At armature 863 the deenergization of relay 860 30 opens the locking circuit of relay 810 whereupon relay 810 deenergizes and at armature 814 opens the circuit of relay 820. All of the relays except relay 880 release and when all of the switches in the controller are restored relay 880 deenergizes 35 and disconnects ground at armature 881 from the conductor 629 to mark the controller idle so that the same may now be used on another call.

- Considering now a case in which the connector encounters a busy line instead of an idle line. 40 In case the line is busy, wiper 474 encounters a grounded bank contact instead of a bank contact having negative battery potential thereon, and therefore test relay 440 is short circuited from ground on the test contact of the called line to grounded armature 431. Since the test relay 440 does not energize a circuit is completed for holding relay 830 energized as follows: from ground by way of off normal springs 468, armature 453 and resting contact, armature 462 and working contact, armature 446, armature 423, through the low resistance winding of relay 430, resting contact and armature 455, conductor 368, through the second and third selectors to conductor 258, wipers 276, conductor 286, armature 55 812 and working contact, conductor 784, armature 772, conductor 785, armature 824 and through the winding of relay 830 to grounded battery. Relay 830 is held energized over the aboved traced circuit and at armature 832 maintains relay 810 in energized position. Relay 810 at armature 815 maintains the circuit to relay 740 open with the result that after approximately four second slow to release relay 750 deenergizes to transmit busy tone to the calling subscriber 65 as previously described. In response to the deenergization of relay 750 ground is disconnected from the control leads 266 and 366 of armature 751 thereby causing the release of relays 330 in the selectors, and relay 460 in the connector. At armature 333 relay 330 closes the restoring circuit for the first selector as follows: ground by way of off normal springs 316, armature 324, interrupter spring 339 and resting contact, armature 333 and through the winding of motor magnet 337 to grounded battery. The second selec-

tor is also restored in the same manner. Relay 460 deenergizes when ground is removed from conductor 366 and at armature 462 opens the circuit to relays 420 and 430 and closes the restoring circuit for the connector. Relays 420 and 430 deenergize and open the circuit to test relay 440 to prevent its operation during the restoration of the wipers. The restoring circuit may be traced as follows: from grounded off normal springs 468, armature 453 and resting contact, armature 462 and resting contact, interrupter spring 416 and resting contact, through the winding of motor magnet 415 to grounded battery. Magnet 415 operates in the manner of a buzzer to restore the switch wipers to their 10 normal position in which position the off normal springs 468 opens the restoring circuit.

In the call controller slow to release relay 750 deenergizes shortly after armature 741 fails to make contact with springs 743 and 744 to transmit busy tone to the calling subscriber as previously described, and at armature 754 opens the circuit of relay 770. At armature 772 relay 770 opens the circuit of relay 830 which accordingly deenergizes.

When the calling subscriber hears the busy tone and hangs up relays 730, 760, 720, 870, 840, 710, 700, 850, 810, 899 and 880 deenergize as previously described.

The release of the call controller after a completed connection between the calling and called lines will now be described. After the connector has cut through and connected the called line relays 440, 450 and 460 of the connector are in energized position and relays 210, 220, 230 and 240 in the secondary relay group are also energized. In the call controller it will be remembered that the circuit to relay 720 was opened in response to the wiper 913 passing from its fifth position into engagement with its sixth position. Relay 720, upon deenergizing at armature 722 opens the circuit of relays 770, 700 and 710. Relay 770, upon deenergizing, at armatures 771 and 772 disconnect ground and battery through the winding of relay 830 from the negative and positive talking conductors in the secondary relay group; at armature 773 temporarily completes a circuit by way of grounded armature 752, conductor 288, and interrupter springs 289 through the winding of motor magnet 290 to grounded battery for automatically stepping the wipers of the secondary trunk finder until slow to release relay 750 deenergizes; at armature 774 opens the original energizing circuit for relay 210 now held energized at armature 222; at armature 775 opens the spark quenching circuit to the motor magnets of the secondary line finders; at armature 776 opens a point in the circuit to relay 790; at armature 777 opens a point in the circuit through relay 780; and at armature 778 disconnects direct ground from conductors 285, 256, 156, and 356 but conductors 156, 256 and 356 are now grounded by way of armatures 213 and 214 and armatures 241 and 243. Relay 710, upon deenergizing, at armature 712 disconnects ground from conductors 624 and 115 but the latter conductor 115 is now grounded from the secondary trunk relay group by way of armatures 213 and 214, conductor 156, wiper 155 to conductor 115, to maintain the cut-off relay 20 in the line circuit in energized position. At armature 714 relay 710 opens the spark quenching circuit to the primary motor magnet 118; at armature 715 prepares a circuit for the upper winding of relay 740; and at armature 716 dis-

- connects ground from conductor 629 to make the controller selectable in case relay 880 is at this time deenergized. Relay 700, upon deenergizing, at armature 701 opens a circuit to relay 780, which accordingly deenergizes; at armatures 703 and 704 opens the circuit to the controller line relay 730 which likewise deenergizes; at armature 705 prepares a circuit to relay 710; and at armature 706 prepares the stepping circuit to primary motor magnet 118. Relay 780, upon deenergizing, at armature 781 prepares the circuit to relay 790 and at armature 782 short circuits itself from grounded armature 791. The call controller line relay 730, upon deenergizing, at armature 731 opens the circuit to relay 760. Relay 760, upon deenergizing, at armature 761 opens a point in the tone circuit; at armature 763 removes the shunt from around armature 766; at armature 764 opens the circuit of relay 140 10 which accordingly releases its weighted armature to start weighted armature 741 vibrating between its springs 743 and 744; at armature 765 opens the circuit to relay 870 and at armature 766 disconnects ground from conductor 798 to de- 15 energize the motor magnet 929 of the sequence switch SS. Relay 740, upon deenergizing, releases its weighted armature 741 which vibrates for approximately four seconds after slow to release relay 760 deenergizes. Relay 870, upon de- 20 energizing, at armatures 872, 875, 877, 878, 879 and 882 closes the self restoring circuits of switches CS, X, SS, RA, RB, RC, and RD, as previously described, in series with relay 880. Relay 880, at armature 881 maintains the controller 25 busy until all of the switches are released by grounding conductor 629 at armature 881. When all of the switches are restored to their normal position and their off normal springs opened as previously described, relay 881 deenergizes to 30 disconnect ground from conductor 629 whereupon this call controller may be used on subsequent calls. From the foregoing description it will be seen that the call controller is only used during the establishment of a connection and as 35 soon as the connection between the calling and called subscribers' lines has been completed the call controller is released for use on other calls.

The release of an established connection between a calling and called subscriber will now be 40 described. From the foregoing description it will be remembered that the established connection is maintained due to the operated condition of the relays in the secondary trunk relay group. It will now be assumed that the called party replaces his receiver with the result that the circuit to the back bridge relay 230 is opened and therefore this relay deenergizes. At armature 231 relay 230 opens the original energizing circuit of relay 240 but relay 240 is now held energized from grounded armature 213 by way of armatures 214 and 243. When the calling subscriber replaces his receiver the circuit through line relay 220 in the secondary trunk relay group is opened whereupon said relay deenergizes. At 45 armature 222 relay 220 opens the circuit of relay 210 which accordingly deenergizes after an interval. Relay 210, upon deenergizing, at armatures 212 and 215 opens a further point in the circuit to relay 220 and at armatures 211 and 216 opens a further point in the circuit to back bridge relay 230. At armatures 213 and 214 relay 210 disconnects ground from conductors 156 and 256 to open the holding circuit of cut-off relay 20 in the line circuit, relay 240 in the secondary trunk relay group, test relays 330 in both

first and second selectors, and relay 460 in the connector. Relay 20 in the calling line circuit deenergizes and restores the line circuit to normal condition. Relay 240 in the secondary trunk relay group deenergizes to prepare the ring back 5 circuit and to disconnect ground from the meter conductor 154. Relays 330 in the first and second selectors close their armature contacts 233 to close the previously described self restoring circuits to restore such selectors to their normal 10 positions. In the connector shown in Fig. 5 relay 460 deenergizes and at armature 461 opens the locking circuit of relay 450. At armature 462 relay 460 prepares the restoring circuit of the connector and at armature 463 disconnects 15 one of the grounds which is holding the test relay 440 in energized position. In case the called party has released relay 450 now deenergizes and at armature 453 opens the holding circuit of test relay 440 at its working contact and at its resting contact completes the self restoring circuit of the connector as previously described. Relay 440, upon deenergizing, at armature 441 reconnects the line relay 410, and at armature 444 disconnects ground from conductor 53 to deener- 20 gize the cut-off relay in the called line circuit corresponding to relay 20 in the calling line circuit. In response to the completion of the restoring circuit motor magnet 415 automatically steps the wipers of the connector as previously 25 described until the off normal springs 468 are opened.

The release of an established connection is somewhat different in case the calling party is the first to replace his receiver. In this case, when 35 the calling subscriber replaces his receiver line relay 220 deenergizes and opens the circuit to relay 210 at armature 222. Relay 210, upon deenergizing, at armatures 211 and 215 opens the circuit of back bridge relay 230 which according- 40 ly deenergizes. At armature 213 relay 210 disconnects ground from conductor 156 to deenergize the cut-off relay 20 in the calling line circuit. Relay 230, upon deenergizing, at armature 231 opens the circuit of relay 240 and likewise disconnects ground from conductor 256. The disconnection of ground from conductor 256 causes the release of the selector relays 330 and relay 460 in the connector. The relays 330 in both selectors again complete the restoring circuit of such 50 selectors whereupon the first and second selectors are restored to their normal positions. Relay 460 in the connector deenergizes and at armatures 461 and 465 completes a circuit through the called substation loop for holding relay 450 in energized 55 position in case the called subscriber has not replaced his receiver. This circuit may be traced as follows: from ground by way of armature 445, armature 456 and resting contact, wiper 478, conductor 52 through the called substation loop, conductor 51, wiper 472, resting contact and armature 461, armature 454, through the upper winding of relay 450 to battery. Relay 450 is therefore held energized over the calling subscriber's loop, until such subscriber replaces his receiver. Relay 440 is likewise held in energized 60 position in order to prevent a call controller from being taken into use the same as if a subscriber had initiated a call. When the called subscriber replaces his receiver the circuit to relay 450 is opened with the result that this relay and relay 440 deenergize and cause the restoration of the switch wipers in the same manner as previously 65 described.

Incoming trunk calls

In order to describe trunk calls between a distant exchange and the local exchange it will be assumed that a calling subscriber in a distant exchange wishes to call subscriber B in the local exchange. The distant exchange switches and apparatus is assumed to be similar to the local exchange just described, and therefore the initiation of a call by the distant subscriber takes an idle call controller in the distant exchange into use. In response to the calling subscriber dialing the digits corresponding to the telephone number of station B, the distant call controller registers and stores the digits. In the same manner as previously described the call controller retransmits the first digit to a first group selector in the distant exchange which operates to select an idle trunk extending to the local exchange. It will further be assumed that the trunk taken into use is the trunk shown in Fig. 10. In order to easily describe the circuit operation, it will be assumed that the call controller shown in Figs. 6, 7, 8 and 9 is located in the distant exchange.

It will be remembered that at the time a first group selector switches through negative battery from the battery feed relay 830 in the call controller is connected to the positive conductor corresponding in this case to conductor 507 over the following circuit: negative battery through the winding of relay 830 by way of armature 824, conductor 785, armature 772, conductor 784, working contact and armature 812, conductor 286, wiper 276, conductor 258, through the operated armatures of the test relay corresponding to test relay 330 in the distant first group selector to either wiper 347 or 348 one of which is in engagement with the bank contact terminating conductor 507 of the trunk line. Ground is connected to the negative trunk conductor 505 from the call controller as follows: ground by way of armature 771, conductor 783, working contact and armature 811, conductor 287, wiper 277, conductor 252, through the upper armature of the test relay in the distant first group selector to either wiper 341 or 342 of the distant group selector to the bank contact terminating the trunk conductor 505. In response to the connection of negative battery to positive trunk conductor 507 marginal two-step relay 500 operates all of its armatures through its second step. At armature 501 relay 500 disconnects the resistance 504 and negative battery from control conductor 506, and at armature 502 locks itself to grounded control conductor 506 before armature 503 opens its original energizing circuit.

Shortly after relay 830 in the distant controller energizes, the relays in the call controller operate in the same manner as previously described to reverse the battery and ground connections to the negative and positive trunk conductors 505 and 507. As previously stated, relays 510 and 520 are polarized relays and will only energize in response to current flowing in a certain direction thereto. At this time a circuit may be traced for energizing polarized relay 520 as follows: from ground by way of armature 771, conductor 783, resting contact and armature 812, conductor 286, wiper 276, conductor 258, test relay armature and wiper of the first group selector through conductor 501, the lower left-hand winding of repeating coil RC, winding of polarized relay 510, high resistance 512, winding of polarized relay 520, upper left-hand winding of repeating coil RC, conductor 505, wiper and test relay armature of the first

group selector to conductor 252, wiper 277, conductor 287, armature 811 and resting contact, conductor 784, armature 772, conductor 785, armature 824, and through the winding of relay 830 to battery. Due to high resistance 512 relay 830 does not energize in this circuit and neither does the polarized relay 510 because the direction of current flow is in the wrong direction to energize relay 510. Polarized relay 520, however, energizes over the above traced circuit and at armature 521 completes the circuit for relay 550. Relay 550, upon energizing, at armatures 551 and 553 reverses the line conductors 562 and 568 with respect to the negative and positive conductors of the repeater. At armature 552 relay 550 completes an obvious circuit for energizing relay 540, and also at armature 552 connects negative battery to conductor 562 to energize the line relay in the second selector over the following circuit: from ground by way of the resting contact on the upper armature of the two-step relay in the second group selector, through the lower high resistance winding of the line relay in the second selector, the armature on two-step relay corresponding to armature 323, through the upper low resistance winding of the line relay, resting contact and armature corresponding to armature 331, conductor 562, armature 551 and working contact, upper right-hand winding of repeating coil RC, through the upper winding of marginal relay 530, armature 552 to grounded battery. Due to the high resistance winding of the line relay marginal relay 530 in the repeater will not energize in series therewith. The line relay in the second group selector, however, energizes to operate the second group selector in the same manner as previously described for the first group selector. Relay 540, upon energizing, at armature 541 grounds the control lead 566 to energize the two-step relay in the second group selector in its first step in a manner similar to that previously described. In the second group selector shown in Fig. 10 the two-step relay therein corresponding to relay 320 energizes and operates only its armature 324 to open the restoring circuit. The energization of the line relay in the second group selector completes the circuit for the motor magnet therein, and the motor magnet positions its pawl preparatory to stepping the wipers and at its interrupter springs opens its own circuit in case the group wiper of the second selector in Fig. 10 is not engaging a grounded group bank contact. Whenever the group wiper in the second selector engages a grounded bank contact the lower high resistance winding of the line relay is short circuited to allow the marginal relay 530 of the repeater to energize. In order to trace this circuit it will now be assumed that the first group selector shown in Fig. 4 is actually in this instance the second group selector shown in Fig. 10. In this case the circuit for energizing the marginal relay 530 in the repeater may be traced as follows: from ground by way of armature 312, interrupter spring 339 and its working contact, armature 323, through the upper low resistance winding of line relay 310, resting contact and armature 331, conductor 562, armature 551 and working contact, upper right hand winding of repeating coil RC, through the upper winding of marginal relay 530 and by way of armature 552 to grounded battery. Relay 530, upon energizing, at armature 531 short circuits the high resistance 512, thereby allowing the marginal relay 830 in the controller to energize over the circuit previously traced for relay 520. The relays in the

call controller now operate in their group finding cycle and the second selector operates from group to group in the same manner as previously described. It being understood, of course, that 5 each time a new grounded group bank contact is encountered by the group wiper of the second selector that the high resistance winding of the line relay is shorted out with the result that relay 530 in the repeater is energized to short circuit 10 the resistance 512 which allows relay 830 in the call controller to energize. The counting switch CS in the call controller is operated step by step for each grounded group bank contact encountered by the second selector and when the counting switch encounters the marked contact, as determined by the digits stored, relay 860 in the call controller will energize to operate the reversing relay 810 in the call controller. At armatures 811 and 812 relay 810 reverses the connections of ground and battery to the negative and positive conductors 505 and 507 with the result that polarized relay 510 instead of relay 520 is now energized and relay 520 deenergizes. Relay 510, upon energizing, at armature 511 maintains 25 the circuit to relay 540 complete and also maintains grounded battery connected to the upper talking conductor of the trunk line. Polarized relay 520, upon deenergizing, at armature 121 opens the circuit to the reversing relay 550, 30 whereupon the latter relay deenergizes. At armatures 551 and 553 relay 550 reverses the battery and ground connections to conductors 562 and 568 to energize the two-step relay in the second group selector corresponding to two-step relay 320 as follows: from ground through the operated off normal springs of the second group selector, lower winding of the two-step relay to the normally closed springs controlled by the lower armature of marginal test relay, conductor 568, 40 armature 553 and resting contact, upper right-hand winding of repeating coil RC, through the upper winding of marginal relay 530 and by way of armature 511 to grounded battery. Relays 530 and the two-step relay in the group selector energize over the above traced circuit. Two-step relay in the second group selector energizes and automatically steps the wipers as previously described for the first group selector until an idle connector is reached at which time the test relay 45 in the second group selector corresponding to test relay 330 operates to switch through to the connector. At the lower armature of the test relay in the second group selector the circuit to the two-step relay and relay 530 in the repeater is opened. Relay 530, upon deenergizing, at armature 531 removes the short from around the high resistance 512 to cause the release of relay 830 in the call controller. The relay 830 in the call controller is marginal and will not maintain its 50 armature attracted when connected in series with high resistance 512. When the counting switch CS in the controller is restored to normal in response to the energization of relay 860 as previously described, relays 850, 860, 810, 820 and 840 deenergize. Relay 820 deenergizes and at this time, since relay 10 is not energized, battery is connected through the winding of relay 830 to the winding of the line relay 410 over conductor 362, assuming of course, that the connector in 55 Fig. 5 is the connector selected by the second group selector.

From the foregoing it will be seen that the repeater repeats back to the call controller the change in resistance when each grounded group bank contact is encountered by the group wiper

of the selector by the energization of relay 530 which, by short circuiting resistance 512, causes the energization of relay 830 in the call controller. The polarized relays 510 and 520 and relay 559 in the repeater repeats the battery reversals from the controller over conductors 562 and 568 to the second selector. In addition, when the selector switches through the circuit to relay 530 is opened and the latter relay deenergizes to open the short around resistance 512 to cause the deenergization of relay 830 in the call controller. The repeater, therefore, repeats over a two conductor trunk extending between the two exchanges the necessary circuit changes so that the controller and switches operate in the same manner as if the controller and switch train were in the same exchange. 15

The repeater operates in a similar manner to that just described for the balance of the connection. The incoming repeater operates on a loop basis from the distant exchange and repeats 20 the two polarities used to control the second group selector and connector. The connector shown in Fig. 5 is now operated in the same manner as previously described in response to the operations of the distant call controller and the incoming repeater. When the called subscriber answers in response to ringing current relay 450 connects the called line to conductors 362 and 368 thereby completing a circuit for relay 530 in the repeater as follows: from ground by way of 25 the lower winding of relay 530, lower right-hand winding of repeating coil RC, working contact and armature 553, conductor 568, positive talking wiper of the second group selector, conductor 368, over the talking circuit including the heavy 30 talking conductors as previously traced through the called substation loop to conductor 362, negative talking wiper of the second group selector, conductor 562, armature 551 and working contact, upper right-hand winding of repeating coil 40 RC, upper winding of relay 530, and through armature 552 to battery.

Returning now to the call controller, it will be remembered as previously described, that when test relay 440 energized to connect ringing current to the called line said relay at armature 446 opened the circuit to relay 830 in the call controller, which thereupon deenergizes. Also, relays 850 and 860 deenergize when counting switch CS restores to normal and later on relays 810 and 820 deenergize. The deenergization of relay 850 at armature 852 steps the control switch X to its fifth position. Wiper 914 of the sending control switch X in fifth position causes the wipers of the switch X to step to their sixth 55 position as previously described. Wiper 913 on leaving its fifth position opens the circuit to release relay 720 to release the call controller as previously described. Wiper 913 of the sending control switch X in its sixth position completes 60 the circuit to the release relay of the secondary trunk relay group in the distant exchange, corresponding to relay 210. Assuming now that the secondary trunk relay group in Fig. 3 is the relay group in the distant exchange, then the operation of relay 210 connects the calling and called lines, operates line relay 220 over the calling subscriber's loop, and grounds the control leads 156 and 256 to maintain the connection as previously described. Returning now to the repeater at a 65 time when the secondary trunk relay group switches through to connect the calling and called lines and the call controller is disconnected, a circuit is completed for maintaining polar relay 520 in energized position as follows: from ground 70

through the lower winding of marginal relay 230, armature 216, conductor 258, over the positive talking conductor and positive talking wiper of the first group selector to trunk conductor 507, lower left-hand winding of repeating coil RC, winding of polarized relay 510, through the high resistance 512, through the winding of polarized relay 520, upper left-hand winding of repeating coil RC, trunk conductor 505, through the negative talking wiper of the first group selector and negative talking conductor of the first group selector to conductor 252, armature 211, and through the upper winding of relay 230 to grounded battery. Relay 230 does not energize over the above traced circuit on account of the high resistance 512. Relay 520, however, is maintained energized over this circuit and at armature 521 maintains relay 550 in energized position. Now, when the called subscriber answers and relay 530 in the repeater energizes as previously described, such relay at armature 531 again shorts resistance 521, thereby energizing relay 230 in the secondary trunk relay group which in turn causes the energization of relay 240 at armature 231. Talking battery to the calling subscriber is now furnished through the windings of relay 220 over the heavy talking conductors to the calling subscriber, and talking battery to the called subscriber is sent through the windings of relay 530 in the repeater over the heavy talking conductors.

The release of the established connection is controlled from the secondary trunk relay group in a manner somewhat similar to that previously described. Relay 220 deenergizes when the calling subscriber replaces his receiver and at armature 222 opens the circuit to release relay 210. Release relay 210, upon deenergizing, at armatures 213 and 214 disconnects ground from the control leads 156 and 256 and at armatures 211 and 216 opens the circuit to relays 230 and 520. Polarized relay 520, upon deenergizing, at armature 521 opens the release circuit of relay 550, which accordingly deenergizes. At armature 552 relay 550 opens the circuit of relay 540 which deenergizes. At armature 541 relay 540 disconnects ground from the control lead 556 to cause the release of the second selector and connector in the same manner as previously described.

In case the second selector encounters an all trunk busy condition said selector stops on the last trunk in the group in which the group wiper is in engagement with a grounded group contact. As previously described the motor magnet is held energized to short circuit the high resistance winding of the line relay and in this case maintains relay 530 in the repeater in energized position. Relay 530 therefore maintains the short circuit around resistance 512 with the result that relay 830 in the call controller is maintained energized. Relay 830 maintains relay 810 in energized position and therefore the latter relay at armature 815 holds the circuit to relay 740 open to cause relay 750 to release and transmits the busy tone to the calling subscriber as previously described. Relay 750 at armature 751 disconnects ground from the control lead 506 to deenergize relay 500 and at armature 754 opens the circuit to relay 770 which deenergizes. At armatures 771 and 772 the relay 770 disconnects ground and battery from conductors 505 and 507 to deenergize polarized relay 510. Relay 510, upon deenergizing, opens the circuit to relay 540. Relay 540, upon deenergizing, at armature 541 disconnects ground from the control lead 566 to

release the second selector in the same manner as previously described.

In case the connector encounters a busy line then the connector actuates in the same manner as previously described, and in this case, since the test relay 440 does not operate, ground from the off-normal springs 468 holds relay 530 in the repeater energized over the following circuit: from ground by way of off normal springs 468, armature 453 and resting contact, armature 462 and working contact, armature 446, armature 423, through the lower winding of relay 430, resting contact and armature 445, conductor 358, through the lower wiper and lower talking conductor of the second group selector to conductor 568, armature 553 and resting contact, upper left hand winding of repeating coil RC, upper winding of marginal relay 530, and through armature 511 to grounded battery. At armature 531 relay 530 maintains the short circuit around resistance 512 to hold relay 830 in the call controller energized. Relay 830 therefore maintains relay 810 energized and relay 810 in turn at armature 815 maintains the circuit to relay 740 open. Relay 740 deenergizes and after an interval relay 750 and relay 770 deenergize as previously described. As previously described, relay 750 transmits the busy tone to the calling subscriber and opens the circuit to relay 500 which deenergizes. Relay 770 also opens the circuit to polar relay 510 which deenergizes and opens the circuit to relay 540. Relay 540, upon deenergizing, at armature 541 disconnects ground from the control lead 566 to release both the second selector and the connector as previously described. In response to the calling subscriber hearing the busy tone transmitted by the call controller, the calling subscriber replaces his receiver and causes the release of the controller, as previously described.

What is new and is desired to be protected by Letters Patent is set forth in the following claims.

What is claimed is:

1. In a telephone system, a trunk line terminating in an automatic switch, means for automatically advancing the switch in a hunting movement over its bank contacts after the seizure of said trunk line, a local circuit controlled by said switch for stopping the automatic advance of said switch, means for transmitting a signal from said switch over said trunk line each time the automatic advance of said switch is stopped, means responsive to said signal for counting each said stoppage and for again operating said automatic switch advancing means, and means for transmitting a signal from said last means over said trunk line to said switch after a predetermined number of stoppages of said switch, and means in said switch responsive to said last signal for again advancing said switch in its final hunting movement.

2. In a telephone system, an automatic switch, trunk lines arranged in groups accessible to wipers of said switch, a register controller, a circuit connecting said controller and switch, means in said switch controlled over said circuit for automatically advancing the wipers of said switch, means for changing the resistance in said circuit for each group of trunks engaged by said wipers, means in said controller responsive to each change of resistance for temporarily opening said circuit and for thereafter closing said circuit to reoperate said first means, counting means in said controller for counting each change of resistance in said circuit, means controlled by said counting means for reversing battery connections

- over said circuit when a desired group of trunk lines is reached, and means in said switch responsive to said reversed battery connections for continuing the advance of said switch wipers to 5 find an idle trunk line in the desired group.
3. In a telephone system, an automatic switch, trunk lines arranged in groups accessible to wipers of said switch, an incoming trunk line terminating said switch, a circuit including a conductor of said incoming trunk, means in said switch controlled over said circuit for automatically advancing the switch wipers over said groups of trunk lines, a local circuit controlled by said switch for changing the resistance in said first 10 circuit for each group of trunks next engaged by said wipers in the automatic advance thereof, and means for counting each change of resistance to determine the extent of the group hunting movement.
4. In a telephone system, an automatic switch having access to groups of lines, a register controller, a circuit between said switch and said controller over which said switch is controlled to select a desired group, means for reversing battery and ground connections in said circuit in response to said switch reaching the desired group, and means responsive thereto for continuing the movement of the switch to a line in the 15 desired group.
5. In a telephone system, a connector, lines arranged in groups accessible to the wipers of said connector, a register controller, means for setting said controller in accordance with two digits of a number, means in said controller for connecting a potential to one conductor of said connector to start the automatic movement of the wipers of 20 said connector over said groups of lines, means in the connector for transmitting a signal to said controller for each succeeding group of lines to be engaged by the wipers of said connector, means in the controller responsive to said signals for connecting said potential to another conductor of said connector when the number of signals equals the first digit of said number, means in the connector responsive to said last connection for continuing the movement of said wipers and for transmitting a signal to said controller for each line encountered by said wipers in the succeeding group of lines, said signal responsive means 25 in said controller again operated in response to said last signals for again connecting said potential to said other conductor when the number of last transmitted signals equals the second digit of said number, and means in said connector responsive thereto for completing a testing circuit for the line engaged by the wipers of said connector.
6. In a telephone system, a connector, lines arranged in groups accessible to the wipers of said connector, means controlled over an incoming conductor of said connector for automatically stepping the wipers thereof in a hunting movement, and means controlled over another incoming conductor of said switch for first indicating 30 when a desired group is reached and for later indicating when a desired line in the desired group is reached.
7. In a telephone system, a selector, trunks arranged in groups accessible in the banks of said selector, a register controller, means for setting said controller in accordance with a number, means in said controller for connecting a potential to one of the conductors of said selector to start the automatic movement of the wipers of said selector over their bank contacts, means in said 35

selector for transmitting a signal to said controller for each succeeding group of lines to be engaged by the wipers of said selector, means in said controller responsive to said signals for connecting said potential to another conductor of said selector when the number of signals equals said first number, and means in said selector responsive to said last connection for continuing the movement of said wipers until they engage the contacts terminating an idle trunk in the corresponding group. 5

8. In a telephone system, an automatic switch, trunk lines arranged in groups accessible to the wipers of said switch, means controlled over an incoming conductor of said switch for automatically stepping the wipers thereof in a hunting movement, and means operated over another incoming conductor of said switch when a desired group of trunk lines is reached for automatically stepping the wipers of said switch until an idle trunk line 10 in the desired group is reached. 15

9. In a telephone system, groups of lines, an automatic switch having access to said groups of lines, a trunk line terminating said switch, means for automatically advancing the switch in a hunting movement over said groups of lines after the seizure of said trunk line, means for transmitting a signal from said switch over said trunk line in response to said switch reaching the last line in each group, means for counting each transmitted signal and for transmitting a control signal back over said trunk line to said switch after a predetermined number of signals have been transmitted from said switch, and means in said switch responsive to said control signal for continuing the advance of said switch to select an idle line in the next group of lines. 30 35

10. In a telephone system, an automatic switch, lines arranged in groups accessible in the banks of said switch, marked bank contacts designating said groups, a trunk line terminating in said switch, means for automatically advancing the wipers of said switch in a hunting movement over their bank contacts after the seizure of said trunk line, means for transmitting a signal from said switch over said trunk line in response to each engagement of the group wiper of said switch with a marked group bank contact, means for counting each transmitted signal and for transmitting a control signal back over said trunk line 40 45 to said switch after a predetermined number of signals have been transmitted from said switch, and means in said switch responsive to said control signal for continuing the advance of said wipers to select an idle line in the corresponding group of lines. 50 55

11. In a telephone system a register controller for registering the digits of a called subscriber's number, a train of automatic switches for extending a connection to the called subscriber's line, a circuit connecting the register controller successively to the switches in said train as the call progresses, means in each of said switches controlled over said circuit after connection therewith for automatically stepping the wipers 60 65 of each switch in a hunting movement, means for counting the groups of trunks and lines engaged by the said switch wipers in their hunting movements, and means in said controller for reversing battery connections over said circuit to the switches in said train in accordance with each registered digit to determine the extent of hunting movement of each switch in the train. 70

12. In a telephone system, primary and secondary finders comprising only wipers and motor 75

5 magnets for operating their associated wipers, and means including a call controller common to all said finders for controlling the operation of the primary finders to find calling lines and for controlling the operation of the secondary finders to find the primary finders taken into use.

13. In a telephone system, a plurality of groups of lines, a plurality of groups of primary finders, each group of primary finders individual to a 10 group of lines and having access thereto, a group of secondary finders having access to said plurality of groups of primary finders for extending connections, and a plurality of register controllers common to said plurality of groups of lines for controlling the operation of said primary and 15 secondary finders to find calling lines and extend connections in the direction of called lines in response to initiations of calls by calling lines.

14. In a telephone system, a repeater, an incoming circuit terminating one end of said repeater, an outgoing circuit terminating the other 20 end of said repeater, means for changing the resistance in said outgoing circuit, means in said repeater responsive thereto for repeating said change by changing the resistance in said incoming circuit, means for reversing battery in the incoming circuit, and means in said repeater responsive thereto for repeating said battery reversal by reversing battery in said outgoing circuit.

30 15. In a telephone system, a train of automatic switches for extending a connection from a calling line, each switch comprising a bank of contacts and associated wipers together with a stepping mechanism for advancing the wipers, a register controller for receiving the called number and for controlling said switches in accordance therewith, means in each switch for controlling said register controller so that the switches are operated according to the revertive system of control, and means for automatically releasing the operated ones of said switches and for transmitting a busy tone to the calling subscriber from said register controller in case any one of said 40 switches encounters an all trunk busy condition or if the called line is busy.

50 16. In a telephone system, a train of automatic switches for extending a connection from a calling line, each switch comprising a bank of contacts and associated wipers together with a stepping mechanism for advancing the wipers, a register controller for receiving the called number and for controlling said switches in accordance therewith, means in each switch for controlling said register controller so that the switches are operated according to the revertive system of control, and means for automatically disconnecting said register controller from said switch train in response to the last switch in said 60 train switching through on an idle called line.

65 17. In a telephone system, a plurality of groups of lines, a plurality of primary finders individual to each group of lines, a plurality of register controllers common to all said groups of lines, means for taking an idle register controller into use in response to a line in one of said groups calling, a group finder individual to each register controller having access to all said primary finders, means for operating the group finder individual to the 70 register controller taken into use to select an idle primary finder having access to the group containing the calling line, means for operating the selected primary finder to find the calling line, a plurality of secondary finders for extending a connection from the calling line, each second-

ary finder having access to all said primary finders, a trunk finder individual to each register controller having access to all said secondary finders, means for operating the trunk finder individual to register controller taken into use to select an idle secondary finder, and means for operating the selected secondary finder to find the selected primary finder.

5 18. In a telephone system, a plurality of groups of lines, a plurality of finders individual to each group of lines, a plurality of register controllers common to all said groups of lines, means for taking an idle register controller into use in response to a line in one of said groups calling, a group finder individual to each register controller 10 having access to all said plurality of finders, means for operating the group finder individual to the register controller taken into use to select an idle one of said finders having access to the group containing the calling line, and means for 15 operating the selected finder to find the calling line.

19. In a telephone system, a plurality of groups of lines, a plurality of finders individual to each group of lines, a plurality of register controllers 20 common to all said groups of lines, means for taking an idle register controller into use in response to a line in one of said groups calling, a group finder individual to each register controller having access to all said plurality of finders, means for operating the group finder individual to the register controller taken into use to select an idle one of said finders having access to the group containing the calling line, and means for 25 operating the selected finder to find the calling line.

30 20. In a telephone system, groups of lines, a register controller common to said groups, a plurality of secondary trunks for extending calls from 40 calling to called lines, means responsive to a call on a line in one of said groups for taking said controller into use, a group finder individual to said controller operated responsive thereto for marking the group containing the calling line, a second 45 finder individual to said controller operated responsive to taking said controller into use for finding an idle one of said secondary trunks, a secondary finder individual to the selected secondary trunk, means for operating said secondary 50 finder to find the group marked by the group finder, and means for connecting the calling line to said selected secondary trunk over said secondary finder.

55 21. In a telephone system, a plurality of primary trunks, means responsive to the initiation of a call by a calling subscriber for taking one of said primary trunks into use, a plurality of secondary trunks, means also responsive to the initiation of said call for taking an idle secondary 60 trunk into use, means for connecting said primary trunk to the calling line, a source of alternating current, means for connecting said source to said primary trunk to mark the same after connection with said calling line and after the selection of an idle secondary trunk, means for connecting the selected secondary trunk to the marked primary trunk after the connection of the primary trunk with the calling line, an alternating current relay operated over said marked 70 primary trunk from said source responsive to said connection, and means controlled by said relay for disconnecting said source from said primary trunk to erase said marking.

75 22. In a telephone system, a plurality of trunks,

- means for selecting an idle one of said trunks, a source of alternating current, means for marking the selected trunk by connecting said source thereto, a finder having access to said trunks, means for operating said finder in search of said marked trunk, an alternating relay operated over said marked trunk from said source in response to said finder finding the same, and means controlled by said relay for disconnecting said source from said 10 trunk to erase said marking.
23. In a telephone system, groups of lines, a plurality of finders individual to each group of lines, a motor magnet in each finder, a circuit for operating each motor magnet to advance its 15 associated wipers step-by-step in search of a calling line, each circuit including interrupter springs on its associated magnet for interrupting said circuit, and a spark quenching circuit common to all said motor magnets for quenching the spark in the motor magnet circuits at said 20 interrupter springs.
24. In a telephone system, an automatic switch, lines arranged in groups accessible to the wipers of said switch, a register controller, a 25 circuit connecting said controller and switch, means in said switch controlled over said circuit for automatically advancing the wipers of said switch, means for changing the resistance in said circuit for each group of lines engaged by said 30 wipers, means in said controller responsive to each change of resistance for temporarily opening said circuit and for thereafter closing said circuit to reoperate said first means, counting means in said controller for counting each change of resistance in said circuit, means controlled 35 by said counting means for reversing battery connections over said circuit when a desired group of lines is reached, change-over means in said switch responsive to said reverse battery connection for changing the automatic advance of said 40 wipers from group hunting to line hunting, said
- resistance changin means again effective to change the resistance in said circuit for each line engaged by said wipers, said circuit opening and closing means again effective in response to each change of resistance to operate said first means to advance the wipers into engagement with a succeeding line in said desired group, said counting means again effective to count each change of resistance, said battery reversing means again effective to reverse battery connections over said 10 circuit when the desired line is reached, and said change-over means again effective in response to said reverse battery connection for completing a test circuit for the desired line.
25. In combination, two groups of lines, two 15 groups of line finders having access to said groups of lines, respectively, a distributor common to all of said lines and having access to finders in both said groups, means responsive to a calling condition of a line in either group for marking the 20 corresponding group of finders and for causing said distributor to select an idle finder in the marked group, and means for controlling the selected finder to cause it to find the calling line.
26. In combination, two groups of lines, two 25 groups of line finders having access to said groups of lines, respectively, a distributor common to all of said lines and having access to finders in both said groups, means responsive to a calling condition of a line in either group for causing 30 said distributor to select an idle finder and for controlling the selected finder to cause it to find the calling line, and testing means associated with said distributor and operative while the distributor is making a selection of an idle finder 35 for insuring that the finder selected by the distributor belongs to the group of finders having access to the group in which the called line is located.

JOHN E. OSTLINE. 40
